APPARATUS FOR THE SYNCHRONIZING AND SHIFTING OF ROTATING SHIFTABLE TOOTHED ELEMENTS

Charles M. Perkins and Thomas V. McNamara, Kalamazoo, Mich., assignors, by mesne assignments, to Fuller Manufacturing Company, a corporation of Delaware

Filed Mar. 5, 1956, Ser. No. 569,503

57 Claims. (Cl. 74—339)

This invention relates to a method and apparatus for the synchronizing of the speeds, and shifting, of shiftable rotating toothed elements.

In carrying out a program of steadily improving the design of transmission devices, it is a constant objective to continually reduce both the skill and the effort required of the operator in carrying out a shifting operation. This is a constant objective regardless of the particular service involved, whether for passenger automobile use, commercial vehicle use including heavy trucks, in earth moving equipment, cranes, mining machinery, or in any of the many other situations wherein shiftable gearing is utilized. Particularly in transmissions for heavy duty use, such as in heavy trucks or earth moving equipment, it is desirable to reduce as much as possible the skill and effort required of the driver in effecting a shift. On the other hand, presently available fully automatic transmissions have not been entirely acceptable for certain uses, especially heavy duty, because of their high original cost, their difficult and expensive maintenance requirements and their relative inflexibility to meet varying operating conditions.

Therefore, it has long been desirable to provide for said certain uses, such as over-the-road operations, a power operated transmission whose shifting is subject to easy manual selection, said selection being capable of being made by any of a variety of devices chosen to fit given operating conditions, as a push-pull rod, selectable push buttons or other convenient devices.

Further, recognizing the demand in connection with other uses, such as in trucks designed to operate in congested traffic, for fully automatic shifting operations, and the probable spreading of the demand therefor, it is equally desirable to provide a transmission capable of manual selection as above mentioned but which is of such basic design that it can be readily adapted to fully automatic control if and when desired by the simple addition of suitable controlling devices.

Turning now to the making of certain definitions, for the purpose of clarity in discussion but with no intention to limit, it is known that transmissions commonly employ a series of relatively shiftable, rotating, meshable members which are adapted to selectively mesh to provide the desired ratio between the speed of rotation of the input shaft of the transmission and the output shaft thereof. These members may be gears, jaw clutch parts, or other interengaging mechanical members, and will be hereinafter collectively referred to as "toothed elements." The term "shifting" and derivatives thereof shall refer to the act of moving one or more of the toothed elements into meshing engagement with other toothed elements to obtain a desired speed ratio between the input and output shafts of the transmission. To obtain a meshing of a pair of the rotating toothed elements, it is desirable that the toothed elements be moving at approximately the same speeds in order to prevent clashing. The term "exact synchronization" and derivatives thereof shall refer to the condition of the toothed elements to be meshed

2

when they are rotating at such relative speeds that their respective pitch circles, or corresponding parts, are traveling at precisely the same circumferential rates. The process of bringing these rotating toothed elements to be meshed to such relative speeds of rotation shall be hereinafter referred to as "synchronizing." The term "condition of synchronization" as used hereinafter shall refer to a relative speed condition of the toothed elements which may or may not be a condition of exact synchronization. The term "acceptable condition of synchronization" as used hereinafter shall refer to any condition of relative speeds of the toothed elements which will permit their meshing without excessive or unreasonable clashing.

15 One of the most important, but by no means the only, problem involved in providing a transmission for heavy duty operation, whether manually or automatically controlled, is the problem of obtaining an acceptable condition of synchronization of the toothed elements at the moment of effecting a shift. In a transmission intended for heavy duty operation, the toothed elements, shafts and other rotating parts involved are large and thereby possessed of considerable inertia. This makes the problem of synchronizing them during the process of shifting materially more difficult, and by the same token, even more important, than the corresponding problem in transmissions intended for lighter duty, such as in passenger automobiles.

30 In the usual approach to transmission synchronization, means are provided which are actuated at the instant of exact synchronization and the toothed elements to be meshed are then moved as rapidly as possible into meshing engagement with each other, the object being to effect such engagement as close as possible to the instant of exact synchronization of the toothed elements to be meshed. This is satisfactory where a slight amount of time is permissible for accelerating or decelerating the toothed elements being driven by the input shaft during the shifting operation to bring them into an acceptable condition of synchronization with the mating toothed elements connected to the output shaft so that such accelerating and decelerating occurs at a relatively slow rate. However, in any type of operation where a large amount of horsepower is being conducted through the

45 transmission, as in a heavy truck climbing a mountain grade, it is desirable to have the input shaft and output shaft of the transmission disconnected for as short a period as possible and this requires a substantial speeding of the rate of such accelerating and decelerating. Thus, in order to speed the deceleration of the rotating parts driven by the input shaft during an upshift, it has become customary to use a deceleration brake. Here, however, the rate of change of speed becomes so rapid

55 that where shifting is started only upon exact synchronization of the toothed elements to be meshed, it is entirely possible for the meshable toothed elements to become entirely out of an acceptable condition of synchronization even during the fraction of a second required for the gears to move in response to the initiation of the shifting sequence. Previous efforts to avoid this difficulty have, insofar as we are aware, been primarily directed toward increasing the speed at which the toothed elements are moved toward each other upon the attainment of exact synchronization.

60 The present invention, however, approaches the problem by detecting a particular condition of synchronization slightly before, that is, in anticipation of, exact synchronization and initiating the shifting movement at that time, the amount of such anticipation being chosen in a given situation to cause the meshable toothed elements to enter into meshable engagement with each other sub-

stantially at, or slightly ahead of, the instant of exact synchronization of the speeds of rotation thereof.

A further problem with conventional equipment has been the problem arising out of disconnecting the engine from the input end of the transmission by the conventional operation of the clutch. With conventional equipment, this is necessary in order to enable the transmission synchronizers to change the speed of the toothed element on the engine side of any given pair of toothed elements to be engaged sufficiently to enable such pair to attain an acceptable condition of synchronization, it being evident that the motion of the vehicle will keep the propeller shaft operating at a speed during any ordinary shifting sequence which is not within the driver's control. Thus, unless the engine speed is increased or decreased sufficiently accurately to correspond to the change in speed of the input end of the transmission brought about by the shifting operation, either a great load will be placed upon the clutch when it re-engages or an excessive load will be placed upon the transmission parts. In an upshift, this is not too serious since if the accelerator is merely released the engine speed will diminish and thus it will change its speed in the same direction as that which re-engagement of the clutch will bring about. However, in a downshift, this is not true and unless the accelerator is accurately controlled to increase the engine speed by the proper amount, serious shock loads can occur.

Thus, by providing a system wherein the clutch can remain engaged throughout the portion of a shifting operation comprising movement from neutral to a shifted position, it becomes possible not only to effect a more rapid shift, particularly in a downshift sequence, as above set forth but it also becomes possible to do so without placing an excessive shock load upon the parts.

A still further aspect of the problem is that when a shift is initiated upon the attainment of exact synchronization, the meshable toothed elements are necessarily brought into meshing engagement when their respective speeds of rotation are moving away from exact synchronization. Thus, the occurrence of meshing of the toothed elements opposes the normal tendency of the speeds of rotation of the toothed elements to move away from exact synchronization and this accordingly places a substantially greater strain on the parts. On the other hand, if the interengagement of the shiftable parts can be made while the toothed element speeds are approaching exact synchronization, then engagement of the toothed elements will assist synchronization.

Therefore, it is desirable to provide an apparatus, applicable to both manual and automatic shifting devices, which will anticipate the instant of exact synchronization of the toothed elements being meshed sufficiently that by the time the shifting mechanism operates and actually brings the toothed elements into meshing engagement with each other, their speeds will be in substantially exact synchronization, rather than in some indefinite condition not close to exact synchronization. Further, since effecting a shift exactly at the instant of exact synchronization for all conditions of operation is impossible as a practical matter, it is desirable to provide means anticipating the instant of exact synchronization and initiating a shifting operation a sufficient period of time prior thereto that the meshing engagement of the toothed elements being shifted will occur slightly before the point of exact synchronization. Thus, at the moment of engagement of the toothed elements, their relative speeds will be approaching exact synchronization rather than, as in present practice, moving away from exact synchronization.

A still further problem involved in heavy duty transmissions is that when manual shifting is carried out, the shift is often relatively slow because of the limited force available from the operator's hand to effect the shifting. In an operation involving the delivery of a large amount

of horsepower, such as where a heavy truck is climbing uphill, it is highly essential that the interruption of the delivery of the power from the engine to the wheels be held to the shortest possible time interval. Thus, although fully automatic devices for effecting such shifting are not desirable since they are not usually sufficiently flexible to meet the varying load conditions imposed upon heavy duty equipment, a manually shifted device does not ordinarily operate rapidly enough to prevent the engine shaft and the propeller shaft from being disconnected for an undesirably long period of time. Accordingly, it is desirable to provide an apparatus which will be completely under manual control for each stage of its operation but wherein the operation itself is carried out under power so that it will be completed with a minimum period of time wherein the engine shaft is disconnected from the propeller shaft.

While primary reference has thus far been, and will herein continue to be, made to heavy duty use, which for present purposes may be considered to be all vehicular transmissions other than those for passenger cars, and including earth moving equipment, cranes, mining machinery, and similar equipment, and the research efforts resulting in the present invention have had in mind primarily heavy duty use, it should be clearly borne in mind that many of the problems solved by the present invention are also present in passenger car use. Hence, many of the objects of the invention can be carried out in passenger car applications and the scope of the invention should be interpreted accordingly.

Likewise, while one primary purpose has been to provide a system of transmission control which provides manual selection and power shifting, it will be understood that some of the units developed for use with and in such system, particularly including the synchronizing method and apparatus but not limited thereto, are also applicable to and advantageous in other types of transmissions including an automatic transmission, and the portions of the invention relating to such units shall be understood accordingly.

A major object of the invention is to provide a transmission shifting device wherein all shifting operations will be subject to manual selection but will be effected by power.

A further object of the invention is to provide a device, as aforesaid, wherein the manual control requires relatively little skill or effort on the part of the operator.

A further object of the invention is to provide a device, as aforesaid, in which the manual control may be moved into a desired position and then left in that position without waiting for the shifting operation to be completed, and the apparatus will then automatically complete the shifting operation without further attention on the part of the operator, excepting only that in a downshift operation the operator must increase the engine speed sufficiently to make synchronization of the gears possible.

A further object of the invention is to provide a shifting system subject to manual control but carrying out the shifting operation under power, which system will be adaptable for use with a variety of different specific sources of power.

A further object of the invention is to provide a method of shifting a transmission which method includes initiating a shifting operation prior to the instant of exact synchronization of the toothed elements being moved into meshing engagement and thereby engage the toothed elements at a point very close to the instant of exact synchronization.

A further object of the invention is to provide a method for shifting a transmission by which the instant of exact synchronization will be anticipated by the apparatus effecting the shifting and will bring the toothed elements being shifted into engagement with each other.

at a point slightly ahead of the instant of exact synchronization.

A further object of the invention is to provide a device of the general type, as aforesaid, which will anticipate the instant of exact synchronization of the toothed elements being shifted and will initiate such shifting at a point sufficiently prior to the instant of exact synchronization that said elements will become interengaged substantially at the instant of exact synchronization.

A further object of the invention is to provide a device, as aforesaid, wherein the time period by which the instant of exact synchronization will be anticipated by the apparatus initiating the shifting will be the same for each of the available speed ratios of the transmission.

A further object of the invention is to provide a device, as aforesaid, which will automatically accommodate itself to either an upshift or a downshift and anticipate exact synchronization in either case.

A further object of the invention is to provide a device which will be operable by a single, easily moved control which will require the operator's hand to be away from the other controls of the machine involved a minimum period of time or which may, if desired, be adapted for operation by the operator without requiring his hand to move from the other controls at all.

A further object of the invention is to provide a device, as aforesaid, which will be extremely rapid in operation and thereby effect shifting smoothly and with a minimum period of time during which the power from the engine to the propeller shaft is interrupted.

A further object of the invention is to provide a device, as aforesaid, in which the engine will remain connected to certain parts of the transmission throughout the portion of a downshift shifting operation extending from the time the transmission parts are put into neutral condition during the shift from the upper to the lower setting until the transmission parts reach their completely shifted position whereby the engine may be utilized for changing the speed of the parts remaining so connected and thereby eliminate the shock to the driving system which sometimes otherwise occurs upon the engagement of a previously released clutch. In prior practice such a previously released clutch sometimes permitted the engine and the propeller shaft driving parts of the transmission to attain materially different speeds.

A further object of the invention is to provide a relatively simple mechanism for pressure fluid shifting of transmission toothed elements and for returning same to neutral position.

A further object of the invention is to provide a mechanism for returning shifted toothed elements to neutral position from any shifted position, which mechanism involves only a single pressure fluid cylinder.

A further object of the invention is to provide pressure fluid shifting apparatus for a transmission in which pressure fluid may be applied to the apparatus for effecting the next shift to be made and including shift preventing means preventing engagement of the toothed elements in response to said pressure until the toothed elements to be engaged have reached a predetermined condition of synchronization.

A further object of the invention is to provide apparatus in which said shift preventing means and the means returning the main transmission to its neutral position during each shifting operation are the same apparatus.

It is a further object of the invention to provide a device wherein the next shifting operation is pre-energized but the shifting movement is blocked until the toothed elements to be engaged have reached a desirable and predetermined condition of synchronization. When such condition is reached, the blocking condition is removed and the parts will then move with a minimum time requirement into the next shifted position.

A further object of the invention is to provide a

method, as aforesaid, which can be carried out by a variety of different types of apparatus, particularly pressure fluid apparatus or electrical apparatus, as desired, to meet the requirements of a particular operation.

A further object of the invention is to provide a method for effecting shifting of a transmission which can be carried out by relatively simple apparatus.

A further object of the invention is to provide apparatus of the type aforesaid which will be positive and reliable in operation, which will be rugged, and which will not require excessive maintenance.

A further object of the invention is to provide a transmission of the general type aforesaid wherein the parts carrying the heavy load are relatively simple and of well known nature and the parts most likely to require maintenance are relatively small and can, if necessary, be readily removed and replaced bodily.

A further object of the invention is to provide apparatus of the type aforesaid which can be readily serviced by mechanics of ordinary ability and, at least for the most part, by the use of ordinary tools.

A further object of the invention is to provide a device, as aforesaid, wherein the specially made parts are all relatively easy to fabricate and thereby economical to manufacture.

Other objects and purposes of the invention will become apparent to persons acquainted with this general type of apparatus upon reading the following specification and examining the accompanying drawings.

In the drawings:

IN GENERAL

In meeting the above outlined objects and purposes of the invention, there has been provided, in general, a manually operated control which includes control positions representing the various speed ratios (or gear settings) between the input and output shafts of a transmission and intermediate positions between said control positions. When the control passes an intermediate position, it applies a force urging the shiftable parts of the main transmission toward their neutral position and, where desired, simultaneously releases the clutch, thus permitting said force to operate and effect placement of said shiftable parts in neutral position. When the control then reaches a gear setting indicating position, it causes a force to be applied to a selected shift mechanism for urging said mechanism and certain toothed elements in a shifting direction. However, the force urging the shiftable parts toward neutral position still remains in effect and it is of greater magnitude than the force urging the shift mechanism in a shifting direction. Accordingly, the shiftable parts remain in neutral position. Upon the occurrence of a proper signal from a detector unit indicating that the toothed elements which are to be shifted into interengagement to provide the desired gear setting are substantially in a predetermined condition of synchronization, the force urging the shiftable parts toward neutral position will be removed and the force urging the shift mechanism in a shifting direction is then permitted to act. By thus having already initiated the force acting on the shift mechanism in a desired shifting

direction, an extremely rapid shift is obtained when a predetermined condition of synchronization is attained and the neutralizing force is removed. This rapid shift in combination with the use of a countershaft brake on an upshift or with proper increase in engine speed by the operator on a downshift, completes the shifting operation in an extremely short period of time and does so without clashing of the gears and without placing unreasonable shock loads on either vehicle clutch or on any of the running parts thereof.

Further, one aspect of the invention contemplates a detector unit adapted for connection to the input and output portions of the main transmission. Said detector unit functions to provide the said signal which indicates the attainment of a predetermined condition of synchronization by the toothed elements of the main transmission that are to be interengaged. Preferably, but not necessarily in all cases meeting the objects of the invention, the detecting unit is so connected that it will present said desired signal at a point in time slightly ahead of the exact synchronization of the toothed elements in the main transmission, and it will do so on either an upshift or a downshift. This signal is then utilized for effecting the shifting of the main transmission. The predetermined condition of synchronization of the toothed elements about to be shifted occurs slightly ahead of exact synchronization thereof and, accordingly, a short interval of time passes between presentation of said signal and the exact synchronization of the toothed elements. However, by the time the shiftable parts of the transmission are energized and moved to effect interengagement of the toothed elements, the said interval of time will have passed and the toothed elements will have reached a condition of almost exact synchronization and the shift may be completed with a minimum of clashing of the toothed elements. Particularly, it is possible to effect such shifting under these conditions even where the rate of change of speed of the parts being shifted is extremely rapid.

DETAILED DESCRIPTION

Referring first to Figure 1, there is shown, for illustrative purposes only, a schematic representation of an embodiment of the invention utilizing compressed air as its energy source for effecting the shifting operation. Also, solely for illustrative purposes, the device is shown in connection with a five speed forward and one speed reverse transmission but it will be evident that the principles of the invention are applicable to any number of transmission speeds which can be effectively utilized with control by shift rods or similar devices. Still further, for illustrative purposes, it is assumed that the transmission and shifting system here utilized for illustrative purposes operates with a relatively heavy truck, but it will be evident that the principles of the invention can be applied to a transmission adapted for any type of service.

The power transmitting parts

Turning first to the main transmission portion of the device, there is schematically indicated a main transmission 1 having an input shaft 2, an output shaft 3 and a countershaft 4. The input shaft 2 is driven by an engine shaft 6 through a clutch 7. The input shaft 2 supports the leftward end 9 of the output shaft 3 through a pilot bearing 8. A gear 11 is formed on the rightward end of the input shaft 2 and is in constant mesh with a first countershaft gear 12. A second countershaft gear 13 is in constant mesh with a gear 14, said gear 14 being rotatably mounted upon, and with respect to, the shaft 3. Jaw clutch teeth 16 are formed within the gear 11 and jaw clutch teeth 17 are formed within the gear 14. A slider 18 is splined to the shaft 3 in a conventional manner and is adapted for sliding movement therealong to engage one or the other of said jaw clutch teeth 16 and 17, respectively. A yoke 19 is connected to the slider 18

and shift rod 21 and moves said slider in response to movement of said shift rod.

A third countershaft gear 20 is in constant mesh with a gear 22, said gear 22 being rotably mounted upon, and with respect to, the shaft 3. A gear 23 is splined to the shaft 3 adjacent to gear 22 and is capable of axial movement along said shaft. Gear 23 has jaw clutch teeth 24 adapted for engaging the jaw clutch teeth 26 of the gear 22 when gear 23 is in its leftward position on shaft 3. A yoke 27 is connected to gear 23 and to a shift rod 28 and is adapted to move said gear axially in response to movement of said shift rod. A fourth countershaft gear 29 is provided for engagement with external teeth 25 of the gear 23 when gear 23 is in its rightward position on shaft 3.

A fifth countershaft gear 31 on the countershaft 4 is adapted for meshing engagement with a gear 32, said gear 32 being splined to the output shaft 3 and arranged for axial movement therewith. A yoke 33 is connected to gear 32 and to a shift rod 34 and is adapted to move said gear axially along shaft 3 in response to movement of said shift rod. Gears 31 and 32 mesh when the gear 32 is in its rightward position of shaft 3.

The gear 32 is also adapted for engaging reverse gearing (not shown) when said gear is in its leftward position on shaft 3. The reverse gearing is mounted on a reverse shaft (not shown) which reverse shaft may be driven in a conventional manner by the reverse drive gear 36 formed on the countershaft 4.

The output shaft 3 is adapted for driving any desired driven device, such as the propeller shaft (not shown) of a truck.

A countershaft brake 35 is provided in a conventional manner and is here schematically indicated as consisting of inter-leaved plates 37 and 38, the plates 37 being affixed to the countershaft for rotation therewith and the plates 38 being affixed to the stationary frame of the transmission. The plates 37 and 38 are adapted to be moved into frictional engagement by the piston 39 to apply a braking force to the countershaft 4. The piston 39 operates within a cylinder 41 in a known manner.

The clutch 7 between the engine shaft 6 and input shaft 2 is normally engaged and is arranged for disengagement by the rod 42 energized by the piston 43 acting within the clutch release cylinder 44.

The shift rods 21, 28 and 34 are supported in any convenient manner for axial movement relative to the shafts 2, 3 and 4, but the specific means of support are omitted from the drawing to avoid unnecessary complication thereof.

Each of said shift rods has a stop member positioned intermediate its ends, stop 46 being on shift rod 21, stop 47 being on shift rod 28 and stop 48 being on shift rod 34. On the ends of each of said shift rods there is provided a suitable piston, such as the pistons 49 and 51 indicated on the shift rod 21. Each of said pistons is located within a suitable pressure cylinder, such as the cylinders 52 and 53 associated with the pistons 49 and 51, respectively. Thus, pressure appearing in any selected one of said pressure cylinders will constitute a shift energizing force urging the shift rod associated with said selected cylinder in a shifting direction.

A pair of plates 50 and 55 are provided with openings through which the several shift rods extend. The plates are arranged on either side of the stops 46, 47 and 48 and are slideable with respect to the shift rods toward and away from said stops. A fixed stop 45 is schematically indicated as fastened to the frame of the apparatus for limiting the motion of plates 50 and 55 such that when said plates are snugly adjacent to the opposite sides of fixed stop 45, as shown in Figure 1, the several shift rods are in their respective neutral positions.

The plate 55 carries a rod 54 on which is mounted the neutral piston 56, slidably arranged within the neutral cylinder 57. The plate 50 is affixed to the walls of the

neutral cylinder 57. Thus, pressure fluid in the leftward end of the neutral cylinder 57 will urge the cylinder walls leftwardly and the piston 56 rightwardly, which causes the plate 50 to move leftwardly and the plate 55 to move rightwardly until they both contact the stop 45. This effects a movement of all of the shift rods into their respective neutral positions.

A neutral valve 58 includes a cylinder 59 which is connected to, and moves with, the plate 55. Valve 58 also includes a sliding spool 61 which is connected to, and moves with, the neutral cylinder 57. Thus, movement of the neutral piston 56 with respect to the neutral cylinder 57 will also effect movement of the parts of the valve 58. The functions of the neutral valve 58 will appear hereinafter.

The manually controlled selector

The manually controlled selector indicated generally at 62 in this embodiment comprises a director valve 63 and a control valve 64. The control valve 64 consists of a housing 66 having a conduit 67 therein, said conduit being fitted with a plurality of neutralizing ports, one of which is indicated at 68, providing communication between said conduit 67 and the interior of said housing. Said housing 66 is also provided with a plurality of shift ports 69 providing further communication between the several conduits hereinafter indicated and the interior of the housing 66. The several ports 69 communicate with said interior of the housing 66 at points intermediate the ports 68, when measured along the axis of said housing, for purposes hereinafter discussed in more detail.

The slider 71 (Figure 1) of said valve 64 has a central conduit 72 therethrough, said conduit having a T-shaped end comprising branches 73 and 74. The branch 73 is adapted to selectively communicate with one of the several neutralizing ports 68 and the branch 74 is adapted to selectively communicate with one of the several shift ports 69. The slider 71 is adapted to be moved between those positions where the central conduit 72 is connected by branch 74 with one of the ports 69 and other positions where said central conduit is connected by branch 73 with one of the ports 68. To effect such movement, the slider is provided with an operating rod 75 on which is mounted a control knob 76. Thus, when the control knob 76 is in any of the major positions indicated by the broken circles 76a, 76b, 76c, 76d, 76e and 76f, the branch 74 will communicate with one of the ports 69, and when the knob 76 is in the position intermediate any of the above stated positions, then the branch 73 will communicate with one of the ports 68. The slider 71 also has an exhaust opening 70 (Figure 1) adjacent to, and leftwardly of, the branches 73 and 74. Said opening 70 is arranged to communicate with one of the neutralizing ports 68 when the branch 74 is communicating with the next shift port 69 rightwardly of such one neutralizing port.

The director valve 63 consists of a housing 86 and a spool 87 contained therein. Connections thereto are provided as shown in the drawings and as set forth in more detail hereinafter. The operating rod 88 for the spool 87 operates between a pair of stops 89 and 91 to provide two settings for said spool. The operating rod 88 is connected frictionally by a sleeve 92 to the rod 75 of the control valve. Thus, movement of the knob 76 and rod to the right will effect movement of the sleeve 92 rightwardly until such movement is terminated by the stop 91. Because of the slideable mounting of the sleeve 92 on the rod 75, the stop 91 will not restrict further movement of the knob 76 and rod 75 rightwardly. Likewise, movement of the knob 76 leftwardly will move the sleeve 92 also leftwardly to the limit provided by the stop 89, but the stop 89 will not restrict further movement of the knob 76 leftwardly. In this way, each time that the direction of shifting, that is, upshift or downshift, is changed, the spool 87 of valve 63 will be shifted from

one of its positions to the other but so long as a shifting sequence proceeds in the same direction, the position of spool 87 of valve 63 will not be changed nor will it interfere with such sequence.

The speed detector unit

Turning now to the detector unit 100, attention is directed toward Figure 2 for a detailed showing of the construction of one effective embodiment thereof.

In Figure 2 there is shown a housing 101 supporting a main shaft 102 in bearings 103 and 104 and also supporting a countershaft 106 in bearings 107 and 108. Countershaft gears 109, 111, 112, 113 and 114 are affixed to the countershaft for rotation therewith and main shaft gears 116, 117, 118, 119 and 120 are mounted on, and rotatable with respect to, the main shaft, and are in continuous engagement respectively with said countershaft gears. The gears 116 and 109 have the same ratio with respect to each other as the main transmission gears 31 and 32, the gears 117 and 111 have the same ratio with respect to each other as the main transmission, meshable gears 29 and 23, the gears 118 and 112 have the same ratio with respect to each other as the gears 20 and 22, the gears 113 and 119 have a one-to-one ratio with respect to each other corresponding to the direct drive of the main transmission and the gears 120 and 114 have the same ratio with respect to each other as the overdrive gears 13 and 14 of the main transmission.

An indicator actuator 121 is mounted on the main shaft 102 between the gears 116 and 117. An indicator actuator 122 is similarly mounted on main shaft 102 between the gears 118 and 119 and an indicator actuator 123 is mounted on the main shaft adjacent to the gear 120. The indicator actuators are all identical with each other (excepting that in the form shown, actuator 123 has only one set of jaw clutch teeth on one, here the rightward, axial end thereof) and hence a description of actuator 121 will suffice for all of them.

The actuator 121 includes a sleeve 151 circumferentially grooved for reception of a yoke 152. Said sleeve 151 has internal splines 153 which axially slidably, but non-rotatably, engage external splines 155 on a collar 154, which collar is rigidly secured to the shaft 102. The ends of certain of said external splines, at least one but usually several, extend axially to provide two sets of stops 156 and 157 on opposite axial ends of said collar 154. A blocker 158 is adjacent one axial end of the collar 154, is radially coextensive with the collar 154 and has a plurality of blocker teeth 159 extending radially therefrom (Figure 2a). The teeth 159 are of the same circumferential spacing as that of the splines 155 excepting that those of such teeth 159 which would otherwise be aligned with the extended end 157 of the splines 155 are omitted. Thus, said extended end 157 extends into the space between a pair of teeth 159a and 159b which teeth are spaced apart circumferentially twice the distance between teeth 159b and 159c, said latter two named teeth being spaced apart circumferentially a distance equal to the spacing between adjacent ones of the splines 155. Thus, relative rotational movement between the collar 154 and the blocker 158 is limited by interference between the extended end 157 and one of the teeth 159a and 159b and when either of said teeth are lying against the extended end 157, rightward movement of the splines 155, and consequently rightward movement of the sleeve 151, is blocked. However, when the teeth 159 are aligned with the splines 155, as shown in Figure 2a, then the blocking function is removed and rightward movement of the splines 153 with respect to the splines 155 is permitted.

The blocker 158 has a tapered internal opening which surrounds and is rotatably supported by, and upon, the tapered hub 161 of the gear 117. A light spring 161 urges said blocker 158 against said hub and creates friction therebetween. The blocker 163 is similarly

constructed and similarly mounted on and with respect to the gear 116 and the jaw teeth 156. Thus, the blocker 158 and teeth 159 will oppose axial movement of the sleeve 151 in response to urging by yoke 152 until said sleeve, rotating with the shaft 102, reaches substantial synchronism with the gear 117, rotating fixedly with respect to the shaft 106. When synchronism is reached, the blocker 158 ceases to block rightward movement of the sleeve 151 and the sleeve accordingly moves rightwardly in a known manner. This releases the pressure of the blocker 158 against the hub of the gear 117 and thereafter, although there is still some frictional engagement between said blocker and said hub, it is light and the wear is not material. It will be noted that there is at no time any actual toothed engagement between the sleeve 151 and the gear 117. The same applies also to the relationships between the sleeve 151 and the gear 116.

A ratio change device or gear set 124 (Figure 2) is provided on either the countershaft or the main shaft, here the main shaft 102, of the detector unit. One convenient form of this ratio change gear set 124, illustrated in Figure 2, comprises a gear 126 mounted rotatably on the sleeve 127, which sleeve supports a friction drum 128. Said drum and sleeve are rigidly fastened by the screw 129 to the end 131 of the main shaft 102. A spring 132, which surrounds the end 131 and the sleeve 127, bears at its one end against a washer 133 and at its other end against a washer 134. Said spring acting through the washer 134 urges the gear 126 rightwardly as appearing in Figure 2. A further gear 136 is mounted on a bearing 137 which in turn is supported on a stub shaft 138 extending leftwardly from a piston 139. The spacing and arrangement of the parts is such that the spring 132 will normally hold the gear 126 against the drum 128 and thereby establish a connection between said gear 126 and the shaft 102, and at the same time it will hold the gear 136 away from said drum. Pressure introduced on the rightward side of the piston 139 will act through the bearing 137 to urge the gear 136 leftwardly against the drum 128 and simultaneously hold the gear 126 away from said drum, thereby establishing a connection between the gear 136 and the shaft 102. Gears 141 and 142 are fixed to a shaft 143 and constantly engage the gears 136 and 126, respectively. The shaft 143 is supported in bearings 144 and 145 for rotation with respect to the housing 101.

The indicator actuators 121, 122 and 123 are operated, respectively, by yokes 152, 166 and 167. The yokes 152, 166 and 167 are fastened, respectively, to shift rods 168, 169 and 170 (Figure 3) which are mounted slidably within the housing 101 in the usual manner. A pressure cylinder is affixed at each end of each of said shift rods, the cylinders associated with shift rod 169, being shown in elevation at 172 (Figure 2) and in section at 172a (Figure 1). Pressure fluid introduced into a selected one of said cylinders urges one of said shift rods longitudinally for purposes appearing hereinafter. It is to be noted that shift rod 170 is provided with a pressure cylinder 175 at its left end, only, since detector unit 100 is not used for shifting into reverse.

Each of said shift rods has a stop intermediate its ends, of which one appears at 173 (Figures 2 and 3) in association with the rod 169. A pair of plates 174 and 176 are slidably positioned with respect to the shift rods on either side of said stops in such a manner that movement of said plates toward each other will bring all of said shift rods to their neutral position. A trip cylinder 177 is slidably arranged within the upper part 178 of the housing 101 and is connected to the plate 176. A trip rod 179 is arranged within, and is slidable with respect to, the cylinder 177 and is connected through a support mounting 181 to the plate 174. A spring 182, which surrounds the rod 179, is seated at its leftward end against a portion of the cylinder 177 and at its rightward end against a valve spool 183, which is connected to said rod

179. Thus, the action of the spring 182 is to push the cylinder 177 and consequently the plate 176 leftwardly and to push the rod 179 and consequently the plate 174 rightwardly. This urges a constant centering of the stops 173 and thereby urges a constant centering or neutralizing of the several shift rods and their connected shift indicator actuators 121, 122 and 123. Thus, the structure of the trip valve 184 of the apparatus is such that the inlet 186 and the outlet 187 may be interconnected by either a rightward movement of the housing 177 or by a leftward movement of the rod 179, one, but not both, of which movements necessarily follows from movement of any one of the shift rods out of its central position. Thus, when any one of the actuators 121, 122 or 123 enters into a state of synchronism with one of the gears on the shaft 102, if there is pressure on the shift rod connected to said actuator and in a direction toward the gear with which the sleeve of the actuator is substantially synchronous, said shift rod will move in response to said urging and either the cylinder 177 or the rod 179 will be moved to permit communication between the ports 186 and 187.

Other parts and connections

There are three relay valves 191, 192 and 193 (Figure 1) whose structure and function will be further indicated as the description proceeds.

Turning now to the connections between the various parts, a supply of air under pressure, such as from 90 p.s.i. to 120 p.s.i., is indicated schematically at 194. A pipe line or conduit 196 extends from said supply to the inlet port of the neutral valve 58. An exhaust port 197 from the neutral valve 58 is spaced from the inlet port of said valve and exhausts to the atmosphere. A further line 198 is connected to an outlet port of valve 58, positioned intermediate the inlet port and the exhaust port 197. The line 196 also supplies a line 199 which extends to an inlet port of the relay valve 191. Valve 191 has an exhaust port 201 communicating with the atmosphere and an outlet port 202, positioned intermediate said exhaust port 201 and the inlet port, which connects to a line 203, which in turn connects with the leftward end of the neutral cylinder 57. Line 203 also supplies a line 204 which is connected to the inlet port of the relay valve 192. Relay valve 192 includes an exhaust port 206 communicating with the atmosphere. An outlet line 207 connects from an outlet port of relay valve 192 positioned intermediate the port 206 and the inlet port. Said outlet port 207 is connected to the cylinder 44 for operating the clutch 7.

The line 198 (Figure 1) connects with a trip line 208 which in turn connects with the inlet port 186 of the trip valve 184. The outlet port 187 of valve 184 connects through a line 209 to the righthand end of the relay valve 191. A manually operable trip valve 211 is connected between the lines 208 and 209 in parallel with the valve 184. The spring 212 normally causes valve 211 to be closed between line 208 and 209. However, valve 211 can be opened, thus by-passing valve 184, by moving the operating knob 213 rightwardly, as appearing in Figure 1.

A further supply line 214 (Figure 1) extends from the source 194 and enters the inlet port of the relay valve 193 whose function is to prevent pressure from coming onto the shifting cylinders until after it has been well established on the neutral cylinder. Otherwise, an undesirable load would be placed on the interlock mechanism. An exhaust port 216 of relay valve 193 communicates with the atmosphere while an outlet port of said relay valve, positioned intermediate the inlet and exhaust ports, communicates with a conduit 217 which is connected to the central conduit 72 of the slider 71. The rightward end of said relay 193 is connected through a conduit 218 to the conduit 67 within the housing 66 of the valve 64 and the leftward side of the relay 193 is connected by a conduit 219 to a first inlet port 220 of the

valve 63. The leftward side of the relay 191 is connected by a conduit 221 to the conduit 218, and the line 208 is connected by a line 222 to the conduit 219.

5 A line 223 (Figure 1) is connected from the line 204 to a second inlet port 225 of the valve 63. The outlet port 230 of the valve 63, associated with the inlet port 220, is connected by the line 224 to the leftward side of the relay valve 192 for urging the spool thereof rightwardly as appearing in Figure 1. A spring 226 constantly urges said 10 spool leftwardly. A second outlet port 215 from the valve 63 is connected by a line 227 to the cylinder 41 of the countershaft brake 35 and functions to apply said brake when said line becomes pressurized. The third outlet port from the valve 63 is connected by a line 228 to the 15 inlet 229 of the detector unit 100 (Figure 2).

Each of the several lines leading from the shift ports 69 in valve 64, namely, the lines 231 to 236, inclusive, connect respectively to one of the cylinders, such as 52 and 53 (Figure 1), which when energized urge the respective shift rods in a shifting direction. Thus, the line 231 connects with the cylinder 53b, the line 232 connects with the cylinder 52b, the line 233 connects with the cylinder 52a, the line 234 connects with the cylinder 53a, the line 235 connects with the cylinder 52 and the line 236 connects with the cylinder 53.

20 Similarly, the lines 232 to 236, inclusive, are also connected to the cylinders (Figure 1) actuating the detector unit 100, specifically, the cylinders 172b, 175b, 172a, 175a and 175, respectively. The line 231, being the reverse connection, does not need to have a connection in the detector unit 100 inasmuch as no synchronizing of this shift is necessary. Thus, energization of any one of said 25 lines 231 to 236, inclusive, excepting in the case of the reverse gear, will simultaneously energize one of the shift energizing cylinders and one of the detector cylinders.

The gearing in the detector unit is so related to the gearing in the main transmission that the ratios of any two simultaneously energized cylinders are the same. Thus, more specifically, the energization of the cylinder 52b 30 which urges the main transmission in a direction for effecting a shift into first gear is associated with the energization of the cylinder 172b which urges the connection of the sleeve 151 with the blocker 163, said blocker being associated with the gears 116 and 109 and said gears 116 and 109 having the same drive ratio as the gears 32 and 31, respectively, in the main transmission. Other pairs of simultaneously energized parts are similarly related, excepting, again, for the reverse gearing in the main transmission which has no corresponding gearing in the detector unit.

35 The countershaft 106 (Figure 1) of the detector unit is driven by any conventional connection X-X' from the output shaft 3 of the main transmission, and the shaft 143 of the detector unit is driven by any conventional connection Y-Y' from the input shaft 2 of the main transmission. Thus, it will be noted that the shafts 102 and 106 of the detector unit will be constantly turning whenever the input and output shafts of the main transmission are turning and the speed differentials between the input and output shafts of the main transmission will 40 be taken up in the detector unit between the respective gears and the associated sleeves 151.

45 While it will be apparent that different specific kinds of connection may be provided between the detector shafts 102 and 106 on the one hand and the transmission input shaft 2 and output shaft 3 on the other hand, it will be definitely preferable to connect the input shaft 102 of the detector unit as shown by means of shaft 143 to the input shaft 2 of the main transmission and the shaft 106 of the detector unit to the output shaft 3 of the main transmission. By having a single pair of ratio differences between the shaft 143 and the shaft 102, it will be apparent that for any setting of the ratio change device 124 the speed of the shaft 102 will be constant for any given speed of the input shaft 2 regardless of the setting of the shaft.

able devices in the main transmission. Thus, the amount of time between the exact synchronization of the meshing toothed elements of the detector unit and the exact synchronization of the toothed elements of the main transmission parts will be constant for any given rate of speed change of the input shaft 2 and for all settings of the shiftable gearing. This will materially improve both the accuracy of operation of the mechanism and the simplicity thereof.

Normally the drive between the transmission input and output shafts and the respective shafts of the detector unit driven thereby will be a direct drive, but it will be recognized that they may also be driven through any desired fixed ratio.

OPERATION

The operation of the foregoing described device has already been somewhat indicated, but it will be reviewed fully for the sake of completeness. The operation of the individual units will be first discussed and then the operation of the system as a whole.

The main transmission

Turning first to the main transmission, this is entirely conventional and need be only briefly summarized.

The prime mover (not shown) of the vehicle or other device with which the transmission system is being used drives the shaft 6 and this acts through the clutch 7 to drive the input shaft 2. Said input shaft acts through the gear 11 to drive the countershaft 4. Shifting of the slider 18 by actuation of the shift rod 21 will connect one of the gears 11 and 14 to the output shaft 3 and thereby drive said output shaft in either direct drive or overdrive depending upon the connection selected. Movement of the gear 23 by the yoke 27 in response to actuation of the shift rod 28 will connect either the gear 22 or the gear 29 to the shaft 3, depending upon the direction of movement of said shift rod, and thereby place the apparatus in either third or second gear, depending upon the direction of such movement. Movement of the yoke 33 in response to movement of the shift rod 34 will connect either the gear 31 or the reverse drive gear (not shown) with the output shaft 3 and thus effect either first or reverse connection of the transmission depending upon the direction of movement of the shift rod 34.

It will be noted that no synchronizers are used in the main transmission for reasons which will be apparent as this description proceeds.

The detector unit

Turning now to the detector unit 100, and with particular attention to Figure 2, it may be assumed for purposes of present illustration that the main transmission is in first gear and a shift to second gear is in progress. Thus, the shafts 106 and 143 will be in constant motion but at different speeds with respect to each other. Since an upshift is occurring, so that the engine is slowing down and it being desired to indicate synchronization slightly ahead of the actual synchronization of the main transmission, it will be necessary to drive the shaft 102 at a speed slightly slower than the actual speed of the input shaft 2. Thus, no pressure is exerted on piston 139 through port 229 so that the spring 132 is holding the gear 126 against the drum 128. Thus, the connection from the shaft 143 is through the gears 142 and 126 to the shaft 102. Pressure is simultaneously placed on the cylinder 175b for urging the shift rod 168 rightwardly and thereby urging the yoke 152 rightwardly.

Under these circumstances, the gear 117, being driven by the shaft 106 will be rotating at a different speed from the speed of rotation of the sleeve 151. Thus, sufficient rotative pressure is applied to the blocker 158 and through it to the extension 157 to prevent rightward motion of the sleeve 151 in a manner well known

for conventional blocker arrangements. As the input shaft of the main transmission slows down, which may be hastened by use of the countershaft brake 35, the speed of rotation of the sleeve 151 will approach that of the gear 117. These parts will reach substantially exact synchronization at a point in time slightly ahead of the time at which the gears 23 and 29 of the main transmission reach substantially exact synchronization. When the sleeve 151 has reached substantially exact synchronization with the gear 117, the blocker ring 158 ceases to oppose axial movement of said sleeve and the sleeve 151 moves rightwardly under the urging of the pressure in the cylinder 175b. It will be noted that the teeth 153 of the sleeve 151 do not engage anything other than the teeth on the blocker ring 158, their function being completed when the sleeve 151 is permitted to move rightwardly.

Upon the occurrence of such rightward movement of the shift rod 168 (Figure 2), the plate 176 is also moved rightwardly which moves the cylinder 177 rightwardly and compresses spring 182. This establishes communication between the ports 186 and 187 for purposes appearing hereinafter.

When pressure in the cylinder 175b is removed, the spring 182 forthwith moves the cylinder 177 back leftwardly to its neutral position, as shown in Figure 2, and this returns the shift rod 168 to its neutral position, which in turn returns the sleeve 151 to the position shown in Figure 2, which is the position at which said sleeve is free from engagement with either of the blocker members 158 and 163 adjacent thereto.

The other shiftable elements of the detector unit 100 operate in the same manner as the rightward movement above described of the sleeve 151 and hence further description thereof would be merely repetitious and accordingly is omitted.

THE ENTIRE SYSTEM

Neutral condition

Attention will now be directed to the neutral condition of the apparatus as illustrated in Figure 1. In this condition of the apparatus, the clutch 7 is engaged, all of the gears of the main transmission are disengaged, the input shaft 2 is driving the shaft 143 of the detector unit at a speed bearing a fixed ratio to the speed of the input shaft and the shafts 3 and 106 are stationary. Pressure from the source 194 exists in the lines indicated by being blacked in and consists specifically of the following: fluid under pressure from the source 194 is in line 196, passes through the neutral valve 58 to the line 198, thence through the line 208 to, but not past, the trip valve 184. Pressure also extends to, but not past, the manual trip valve 211. Line 196 also energizes line 199 to, and through, the relay valve 191 to the line 203 and thence to the neutral cylinder 57. The line 203 also energizes the line 204 to, but not through, the valve 192. Line 204 energizes line 223 to, and through, the valve 63 and thence energizes the line 228 to the inlet 229 of the detector unit 100. The source 194 also energizes the line 214 to, and through, the relay valve 193 to the conduit 217. This travels through the central conduit 72 within the valve 64 and energizes the conduit 67, which in turn energizes the conduits 218 and 221. The line 222 energizes the conduit 219 for maintaining the spool of the valve 193 in balance, that is, in the position as shown in Figure 1, and the line 222 also conducts pressure fluid to, and through, the valve 63 to the line 224. The line 224 applies pressure to the spool of the relay valve 192 for holding said valve rightwardly. The control valve selector knob 76 is in its full leftward position and the operating rod 88 for director valve 63 is likewise in its full leftward position, inasmuch as the last preceding movement of the knob 76 from any of the shifted positions, including reverse,

was necessarily a leftward movement in order to reach neutral position.

The apparatus is now ready for shifting into a selected driving ratio.

First gear position

Turning now to Figure 4 the control knob 76 is shown moved into first gear position. This has moved the spool 87 of the director valve 63 into its rightward position with the result that lines 228 and 224 have both been disconnected from their pressure source and have been connected with exhaust. However, the trip line 208 has now been connected through line 222 and the director valve 63 with the line 227 and pressure thereby applied to the countershaft brake. The shifting of the knob 76 has also moved the slider of the control valve 64 and has connected the conduit 218 to exhaust and the conduit 217 to the line 232. Pressure in the line 232 applies pressure to the first gear shifting cylinder 52b and simultaneously applies pressure to the cylinder 172b of the detector unit.

Pressure in the neutral cylinder 57 tends to hold the plates 50 and 55 together and thereby tends to hold all of the shift rods in neutral position. Pressure in the cylinder 52b tends to move the shift rod 34 rightwardly. However, even though the source of pressure in both cases is the same, the diameter and effective area of pressure on the piston 56 is greater than that on the piston in cylinder 52b, hence the parts remain in neutral condition.

Conditions are now ready for the actual starting of the vehicle, bearing in mind that it is starting from a standstill, so that the output shaft 3 is accordingly stationary, and that the input shaft 2 has been brought to rest by application of the countershaft brake.

With preparations made as outlined above, the operator now depresses the clutch pedal (not shown) and immediately thereafter he presses the knob 213 of the manual trip mechanism. This, as shown in Figure 5, provides a connection from the trip line 208 through the valve 211 to the line 209. Figure 5 illustrates this condition before any other move has taken place.

Turning now to Figure 6 there is shown the changes which occur as a result of the condition illustrated in Figure 5. The spool of the valve 191 moves leftwardly, blocking the lines 196 and 199 from communication with the line 203 and connecting the line 203 to the exhaust port 201. Release of pressure from the neutral cylinder 57 through line 203 now permits the pressure in the cylinder 52b to move the shift rod 34 rightwardly and thus effect engagement between the gears 31 and 32. Exhausting of the line 203 also exhausts line 204 and line 207 through valve 192, which exhausts clutch cylinder 44. However, since the operator's foot is still on the clutch pedal, the clutch is not yet engaged. The operator now releases the clutch pedal thereby permitting the clutch to engage and the apparatus is in first gear.

As soon as the shift rod 34 moves in response to the pressure in the cylinder 52b, it will effect a separation of the plates 50 and 55. This moves the spool of the neutral valve 58 rightwardly with respect to the cylinder or housing 59 of such valve and thereby breaks the connection between the lines 196 and 198 and connects the line 198 with exhaust through exhaust port 197. This removes the pressure from the line 198 as well as from the line 208 and the line 209. It also removes the pressure from the lines 222 and 227 to release the countershaft brake.

It will be noted that the detector unit 100 played no part in this operation. This is because the vehicle was starting from a standing position so that the output shaft 3 was stationary. Accordingly, the release of pressure from the neutral cylinder took place by operation of the manual trip valve 211 rather than by operation of the detector unit 100 as will be described hereinafter in connection with shifts between two moving conditions.

Shift from first to second gear positions

With the parts in the condition shown in Figure 6, it is now desired to make a shift from first gear to second gear. The first step is illustrated in Figure 7 wherein the control knob 76 is moved from first position 76b to a point halfway between first and second. It will be appreciated that this is only an instantaneous condition inasmuch as it will not be necessary for the operator to cause the knob to pause in this position. The knob will occupy this position a sufficient length of time if the operator merely moves the knob by a continuous motion from first to second gear positions. Nevertheless, for illustrative purposes, the instantaneous condition existing between said positions is illustrated in Figure 7 and will be described.

Under the conditions illustrated, the director valve will not move inasmuch as it is held by the stop 91 and the sleeve 92 merely slides on the rod 75. The slider 71 now connects the conduit 217, which is still pressurized, to the line 67 and this places a pressure in both of the conduits 218 and 221. This will effect a leftward movement of the spool of the valve 193 and a rightward movement of the spool of valve 191, both as shown in Figure 8. The line 232, previously pressurized, is now disconnected from its source of pressure and connected to exhaust. This exhausts the pressure fluid from both shift cylinder 52b and detector cylinder 172b. This permits the spring 182 to return the detector unit to neutral and readies the main transmission for a return to neutral when other conditions are right.

The valves 191 and 193 (Figure 8) have moved into the positions as shown as a result of the condition illustrated in Figure 7 and the valve 192 is in its leftward position as a result of the action of spring 226 in response to the release of pressure from the line 224, as illustrated in Figure 4. The pressure from line 228 also having been previously released, the detector valve, ratio change device 124 is connected between the gears 142 and 126 (Figure 2) in response to the urging of the spring 132, as above set forth. The slider 71 of the control valve 64 now connects its central conduit 72 with the second gear line 233 and its housing conduit 67 is now connected through the passage 70 to the atmosphere.

With the valve 191 moved into its rightward position, pressure from the lines 196 and 199 is again conducted through the line 203 to the neutral cylinder urging it back toward neutral position. Figure 8 shows this movement approximately half accomplished. Pressure is also applied through the line 204 and the valve 192 to the line 207 and the clutch cylinder 44 for the purpose of disconnecting the clutch 7.

Leftward movement of the valve 193 terminates pressure in the conduit 217 and permits same to exhaust through 216.

As soon as the parts attain full neutral position, illustrated in Figure 9, the neutral valve 58 again effects a connection between the line 196 and the line 198 and pressurizes both of the lines 208 and 222. The pressure in line 208 is stopped at the trip valve 184. The pressure in line 222 pressurizes the conduit 219 to return the valve 193 to its rightward position and also pressurizes the line 227 to energize the countershaft brake. The line 204 remains pressurized from the line 203 and this holds the main clutch 7 open. It also pressurizes the line 223 but such pressure is stopped at, and by, the valve 63.

Pressure from the air supply 194 is admitted into the line 217 and thence into the second gear line 233. This energizes the second gear shift cylinder 52a and simultaneously energizes the second gear detector cylinder 175b, urging both of the respectively connected shift rods in a rightward direction. Thus, it will be seen that the shift cylinder 52a, due to the valve 193, is pressurized a sufficient period of time after the pressurizing of the neutral cylinder 58 to avoid undesirable strain on the interlock mechanism.

The rightward pressure on the detector unit shift rod

168 acts through yoke 152 (Figure 1), as above described, to urge its sleeve 151 rightwardly against the blocker ring 158 (Figure 2). Assuming that the inertia of the vehicle maintains the speed of the output shaft substantially constant, it will be recognized that synchronization will be accomplished only upon a slowing of the input shaft 2. As soon as this is accomplished, here primarily by action of the countershaft brake 35, the sleeve 151 will move rightwardly and thereby permit rightward movement of the detector shift rod 168. This effects a rightward movement of the plate 176 and a corresponding rightward movement of the housing 177 which, as above described in more detail, connects the ports 186 and 187. This provides a connection for the line 208 (Figure 10) through the valve 184 to the line 209 for urging the spool of the valve 191 leftwardly. It will be observed that this operation occurs at a point in time slightly ahead of the exact synchronization of the second speed gears of the main transmission because of connection through gears 142 and 126 of input shaft 2 and the main shaft 102 of the detector unit 100. Hence, by the time the operations immediately after synchronization of sleeve 151 and ring 158 are completed, the second speed gears of the main transmission will be substantially at exact synchronization. However, since exact adjustment and exactly predictable operation is not possible as a practicable matter, it is normally preferred to adjust the relative speeds of the shaft 102 and the shaft 143 sufficiently apart that the actual shifting of the main transmission hereinafter described also occurs slightly ahead of the exact synchronization of the gears which are to be engaged.

Referring now to Figure 11, there is shown the situation resulting from the leftward movement of the spool of valve 191. Pressure from line 199 to the neutral cylinder 57 is cut off and the line 203 leading to the neutral cylinder is connected to exhaust through port 201. Likewise, the lines 204 and 207 leading to the main clutch cylinder 44 are also connected to exhaust, thereby permitting the clutch to re-engage. Release of pressure from the neutral cylinder permits the pressure within the second gear shifting cylinder 52a to move the shift rod 28 rightwardly and thereby effect the shifting of the gears into second gear. With the shifting pressure already on the second gear shifting cylinder 52a when the pressure from the neutral cylinder is released, this shift will take place very quickly and sufficiently ahead of the actual re-engagement of the main clutch that no difficulty will be encountered by having both of these operations initiated by the same valve. If desired, however, a one-way restrictor 205 may be placed in the line 204 to slow the pressure build-up in the clutch cylinder 44 sufficiently to insure the engagement of the gears ahead of the clutch re-engagement. As before, movement of the parts into a shifted position will separate the plates 50 and 55 and thereby move the neutral valve 58 to disconnect the pressure line 196 from the line 198 and connect the line 198 to exhaust through port 197. This deenergizes the lines 208 and 209, as well as the lines 222 and 227 leading to the countershaft brake 35, resulting in the release of the countershaft brake. The parts are now shifted into second gear.

Shifts from second gear through fifth gear inclusive

Each of these shifts proceeds in the same manner as above outlined in detail for the shift from first gear to second gear and will be self-evident. Accordingly, no detailed explanation thereof will be necessary.

Shift from second gear to first gear

Turning now to the downshift operations, the same may be illustrated by a shift from second to first, although it will be understood throughout that the same may be taken as illustrative of any other downshift operation.

Commencing with the condition shown in Figure 11, and previously described, the control knob 76 is moved from second position 76c to first position 76b, 76a being

the reverse position. By such movement, it passes through and momentarily occupies the intermediate position illustrated in Figure 12. This simultaneously exhausts the second gear line 233 and pressurizes the conduit 218 and the conduit 221. This moves the spool of the valve 193 leftwardly and the spool of the valve 191 rightwardly to assume the positions shown for these valves in Figure 13.

When the knob 76 reaches its first gear position, pressure is introduced from the line 199 through the valve 191 to the neutral cylinder, thus returning the gears to neutral position, the illustration in Figure 13 showing them part way toward that position. Pressure is also introduced to the main clutch cylinder 44 for disconnecting the clutch 15 to permit release of the presently engaged gears. The leftward movement of the rod 75 has now moved the operating rod 88 of the director valve 63 leftwardly toward stop 89 and pressure in the line 223 is now conducted through the line 228 to the inlet 229 of the detector unit 100. This, as described above in more detail, moves the piston 139 (Figure 2) leftwardly, thus moving the gear 136 against the drum 128 and, by pressure of the gear 136 against the gear 126, moves said gear 126 off from said drum. Thus, the connection from the shaft 143 to the shaft 102 is through the gears 141 and 136. This ratio is such as to cause the shaft 102 to run slightly faster than the input shaft 2 (Figure 13) of the main transmission, whereby to attain a condition of exact synchronization at a point of time slightly ahead of the attainment of corresponding synchronization by the gears of the main transmission. This, again, is for the purpose of initiating the shifting operation during a downshift in a point of time slightly ahead of the attainment of exact synchronization by the gears in the main transmission which are to be engaged by a given shifting operation.

Continued movement of the shift rod 28 toward neutral position under the urging of the neutral cylinder 57 brings the parts to the condition shown in Figure 14. As the parts attain full neutral position, the neutral valve 58 again connects the line 196 with the line 198 and this acts through the line 208 to apply pressure at the port 186 of the valve 184, and also acts through the line 222 and the valve 63, now in its leftward position, to apply pressure to the line 224. This moves the spool of the valve 192 rightwardly and thereby cuts off the pressure to the line 207 and connects said line 207 to the exhaust port 206. Thus, the clutch is re-engaged and remains connected throughout the rest of the downshift operation in order that the driver may utilize the engine directly for rapidly speeding up the rotation of the input shaft 2.

Pressure from the line 222 also passes through the conduit 219 to hold the spool of the valve 193 rightwardly. This conducts pressure from the line 214 through the line 217 into the first gear energizing line 232. From here, pressure is conducted to the first gear cylinder 52b and also to the first gear detector cylinder 172b.

As the input shaft 2 (Figure 14) speeds up, the shaft 102 of the detector unit, running slightly faster than the input shaft 2, will reach a condition of synchronization with the countershaft 106 of the detector unit slightly ahead of the attainment of exact synchronization by the gears 31 and 32 of the main transmission. Such synchronization in the detector will permit leftward movement of the sleeve 151 against the blocker member 163 (Figure 2) and will thereby permit the shift rod 168 to move leftwardly. The attainment of said detector synchronization, in permitting the communication between the ports 186 and 187 as above mentioned, brings about a pressurizing of the line 209 and thereby a movement of the spool of valve 191 into its leftward position. The condition just prior to detector synchronization is shown in Figure 14.

In Figure 15, synchronization of sleeve 151 and blocker 163 of the detector unit has been reached and it is presumed that synchronization of the main gears will be reached a small fraction of a second thereafter. Thus,

by the time the herinafter described movements take place, the main gears will be substantially exactly synchronized and their interengagement will be accomplished smoothly and easily, as shown in Figure 15.

Leftward movement of the spool of valve 191 deenergizes the neutral line 203 and connects it to exhaust. This removes the pressure from within the neutral cylinder 57 and permits the pressure within the first gear shifting cylinder 52b to act immediately to move the shift rod 34 rightwardly and engage the gears 31 and 32. Shifting movement of the shift rod 34 actuates the neutral valve 58 as shown and both cuts off the pressure supply to the line 198 and connects it to exhaust. This deenergizes the lines 208 and 209 and also deenergizes the line 222. The deenergizing of line 222 deenergizes line 224 and permits the spring 226 in valve 192 to return the spool of the valve 192 to its leftward position ready for operation of the main clutch cylinder 44 when desired. Inasmuch as the line 204 is now deenergized, there is no actuation of the main clutch cylinder 44 at this time. The shift into first gear is now completed.

While deenergization of the line 204 at this time also results in deenergization of the lines 223 and 228 and a consequent return of the connection between shaft 143 and shaft 102 to the gears 142 and 126, it will be noted that (with respect to downshifts into other than first gear) the director valve 63 remains in the same condition as previously so that as soon as the next energization of the neutral cylinder 57 occurs, preparatory to the next downshifting operation, the line 228 will again be energized and the gears 141 and 136 will again be the connecting means between the shafts 143 and 102 for so long as a downshift progression continues.

Shift from first gear to neutral

The return from first gear to neutral may be taken as illustrative of the shift from any gear to neutral position and is here chosen solely in the interest of continuity from the previously utilized examples.

The first two stages of the return to neutral position are the same as with any downshift and are sufficiently illustrated and described in connection with Figures 12, 13 and 14. However, the final stage of a shifting into a neutral position provides that pressure from the line 217 (Figure 1) passing through the central conduit 72 of the valve 64 is conducted into the line 221 and not into any of the lines leading to shift cylinders. This holds the pressure from line 199 onto the neutral cylinder and the transmission assumes the condition shown in Figure 1.

Shift from neutral to reverse and from reverse to neutral

This follows the same progression as outlined above in connection with shifting from neutral to first gear and from first gear to neutral, including the use of the manual trip valve 211 instead of the detector unit 100, and for the same reasons. Therefore, this portion of the operation is believed obvious from the description already set forth and further detailing thereof is believed unnecessary.

MODIFICATIONS

Figure 16

Referring now to Figure 16, there is shown a modified apparatus for carrying out the purposes of the invention and capable of obtaining certain advantages. In brief, the apparatus of Figure 16 eliminates the conduit 67 and ports 68 associated with intermediate positions of the control knob 76 as in the above described embodiment of this invention and accomplishes identical results by use of a mechanical control of the valve 193.

In Figure 16 the valve 193 is shown with somewhat different connections thereto than those shown in Figures 1 to 15, inclusive. In Figure 16 those lines and conduits which correspond functionally to the lines and conduits

in Figures 1 to 15, inclusive, but which are specifically differently connected or controlled differently than the lines and conduits in Figures 1 to 15, inclusive, are designated by the same reference numerals as used previously with the addition of the letter "a" thereafter.

In this modification, the line 221a is connected directly to one outlet conduit 216a of the valve 193 and the line 218a is connected to another outlet conduit of the valve 193. The supply line 214a is connected directly to the line 196. The line 219 is connected, as before, to the first inlet 220 of director valve 63.

Any mechanical means illustrated generally at 301 is provided for mechanically moving the spool of valve 193 leftwardly at the beginning of a shifting movement. Thus, as schematically indicated in Figure 16, a shift lever 302 is provided on the shift rod 303, said shift rod being supported for both sliding movement along its axis and limited rotative movement about its axis. These movements are imparted to the shift rod 303 by the shift lever 302 as said lever shifts from a position within one of the notches 304 to another one of said notches. The shift rod 303 is mechanically connected in any convenient manner to the operating rod 75 so that axial movement of the rod 303 will result in similar axial movement of the rod 75. A linkage 306 is connected from said rod 303 to a pawl 307 and said pawl is positioned to actuate the core of valve 193. Thus, a clockwise movement of the rod 303, which is the beginning movement of any shift sequence inasmuch as it is the movement which moves the shift lever 302 out of a notch 304, results in a rightward movement of the pawl 307 to engage it with the hook 308 which is in turn connected to the spool of valve 193. Next, a counterclockwise movement of the rod 303, occasioned as the shift lever enters whatever one of the notches 304 represents the next shifted position, results in a leftward movement of the pawl 307 and a similar leftward movement of the spool of valve 193 to provide the same functions as when said valve spool was moved leftwardly by a pulse of air entering through the line 218 indicated in Figures 1 to 15, inclusive. The wedge 310 then lifts the pawl 307 to release the hook 308 and permit the valve 193 to return rightwardly when the line 219a is pressurized.

Figures 17 through 20

Turning now to Figures 17 through 20, inclusive, there is shown another form of device which may be substituted for the detector unit 100 utilized in the embodiment shown in Figures 1 to 15, inclusive.

This device comprises a frame structure 401 which also functions as a casing or housing for enclosing the operating parts. The upper portion of said frame 401 (Figure 17) includes a series of pairs of axially aligned cylinders 402 and 403 together with a slide receiving cylinder 404. Here there are five pairs of axially aligned cylinders 402 and 403, corresponding to the five forward speeds of the transmission disclosed above. These pairs of cylinders are arranged about the slide receiving cylinder 404 as shown in Figure 18.

The lower part of the frame 401 (Figure 17) at its leftward side contains the bearings 406 and 407 for the support of a first input shaft 413. The lower portion of frame 401 also contains bearings 427 and 428 for the support of a second input shaft 429 which is perpendicular to the axis of shaft 413. The inner end of said input shaft 429 is provided with a friction disk 431 for purposes appearing hereinafter. A spring 432, which encircles shaft 429 between the bearings 427 and 428, seats through the bearing 427 against the shoulder 433, and thereby constantly urges the disk 431 upwardly. The matching shaft 411 carries a synchronizing roller 412 and the first input shaft 413 carries a blocking head 414. The rightward end of the matching shaft is supported by the bearing 408 and the leftward end of said matching shaft 411 is journaled for limited rotation within, and

relative to, the rightward end of the first input shaft 413. A blocking collar 417 is mounted on a portion 418 of reduced diameter near the leftward end of the matching shaft 411 and is arranged to be rotated with the matching shaft 411 by the pin 419 while being permitted axial movement with respect thereto. As shown in Figure 19, a flange 421 is integral with, and limits the leftward movement of, the blocking collar 417 and a blocking wedge 422 extending leftwardly from said flange is receivable within the opening 423 in the collar 415, which collar is mounted on, and for frictional rotation by, the tapered periphery of the blocking head 414. The opposed end surfaces of the wedge 422 and the opening 423 are positioned at an angle with respect to a plane perpendicular to the longitudinal axis of shafts 411 and 413 in order that relative rotative movement of said wedge and said opening will effect relative axial movement thereof. Said opening 423 is circumferentially wider than said wedge to permit said relative rotative movement.

The matching shaft 411 (Figure 17) is provided with a thread and similar threading is provided within the roller 412. Thus, when the roller 412 and shaft 411 are moving at different rotational speeds so that there is a relative rotation between them, there will also be effected an axial movement of said roller on said shaft. From this it follows that if the roller 412 is held against axial movement when such tendency exists, then shaft 411 is required to rotate at the same speed as roller 412. If this speed is not the same as the speed of shaft 413, then slippage will occur between collar 415 and blocking head 414. The frictional relationships of the wheel 412 with respect to the surface of the disk 431 and that of the collar 415 with respect to the blocking head 414 are so related to each other that relative slippage will always take place between the collar 415 and the head 414 and no slippage will take place between the wheel 412 and the disk 431.

A yoke 434 (Figures 17 and 18) engages an annular groove 436 in the roller 412. The yoke 434 is mounted on the slide 437, said slide being mounted for reciprocal axial movement within the slide cylinder 404. A blocking plate 438 is integral with yoke 434 and extends from said slide into a position intersecting the projected axes of each of the several pairs of coaxial cylinders 402 and 403. The cylinders 403 each have a piston 441 therein and each of said pistons has a rod 442 associated therewith.

Each of the cylinders 402 has a piston 443 therein. A rod 444 is affixed to each of said pistons and projects through and beyond a plate 446 in a manner discussed further hereinafter. Thus, it will be seen that the rods 442 and 444 determine the limits to which the plate 438 may travel in a direction parallel with the axes of said rods, which direction is also parallel with the axis of the shaft 411. When fluid pressure is introduced into any of the pairs of cylinders 403 and 402, the corresponding rods 442 and 444 are extended toward, or against, the plate 438 for purposes appearing hereinafter.

A valve structure 184a (Figure 20) corresponding to the valve structure 184 shown in Figures 1 to 15, inclusive, is provided with an inlet 186a and an outlet 187a corresponding in function to the inlet 186 and the outlet 187 of Figures 1 to 15. The valve core 451 is connected through toggle links 452 and 453, which links are constantly urged into valve closing position by the spring 454, to a trigger 456. Said trigger is, in this instance, integral with the link 453 and is mounted on the plate 450. The end of said trigger is provided with a step 457 (Figure 19.) A pair of co-axial spring backed pins 458 and 459 are mounted to oppose each other and to meet normally in approximately the plane of the surface of the trigger 456 opposite the notch 457. The pin 458 is larger in diameter than the pin 459 for reasons appearing hereinafter. A trip 461 is pivoted to the frame at 462 and is connected at one end to the pin 459 and has

a shoe 463 on another portion thereof contacting the back of the flange 421.

The operation of this device, with respect to the rest of the apparatus, is the same in substance as that of the detector unit 100 shown in Figures 1 to 15, inclusive, but its specific operation is entirely different from the operation of said detector unit. The second input shaft 429 is connected to one end of the main transmission, as to the output shaft 3 (Figure 1), by any convenient means, such as a flexible shaft, and the first input shaft 413 is similarly connected to the other end of the transmission, as to the input shaft 2. The respective pairs of cylinders 402 and 403 are connected together and are then further connected respectively to the several lines shown in Figures 1 to 15 as connecting to the cylinders 175, 175a, 175b, 172a and 172b.

In Figure 17, the piston 443 and slide 437 are retracted to permit the roller 412 to move beyond the edge of the disk 431. This comprises the neutral position.

With the shafts 429 and 413 connected as above indicated a shifting movement by the operator will result in energizing of the line 464 corresponding, for example, to the line connected to the cylinder 175 in Figure 1. This pressurizes the pair of cylinders 402 and 403 appearing in Figure 17. This causes pistons 441 and 443 to move toward each other thereby engaging the plate 438 and through it pushing the roller 412 into engagement with the disk 431 at such a point along the radius thereof that there will be no slippage between shafts 413 and 411 when the gears to be engaged are in a predetermined condition of synchronism, usually slightly ahead of exact synchronism. Going from standstill position into first gear, the manual trip valve 211 will need to be operated here in the same manner as it is in the embodiment shown in Figures 1 to 15 in order to move the spool of valve 191 leftwardly. However, when the shift from first to second gear is being made, or between any other pair of gears with the truck, or the vehicle, being in actual motion, the operation will be automatic.

Operation of the selector mechanism will pressurize a next selected pair of the cylinders 402 and 403 and this will extend the corresponding pair of pins 442 and 444 towards each other. One of these pins engages the plate 438 and thereby pushes the roller 412 into such a synchronization detecting position along the radius of the disk that the roller 412 will rotate at the same speed as shaft 413 when the next set of gears to be engaged are in a predetermined condition of synchronism with respect to each other, usually just ahead of exact synchronism. In each case, the reaction between the disk 431 and the roller 412 will hold the plate 438 tightly against whichever of the pins 442 and 444 pushed it into said synchronization detecting position on the disk 431 until said predetermined condition of synchronism is reached at which time it will tend to float free of said pin.

So long as there is a differential between the speed of rotation of the roller 412 and of the shaft 413 there will necessarily be slippage between the collar 415 and the head 414. This will produce a slight relative rotation between the projection 422 (Fig. 19) and the side walls of the opening 423 which will result in rightward movement of the flange 421. This will push the pin 459 downwardly and cause the pin 458, which is of slightly larger diameter than the pin 459 (Figure 19a), to move downwardly sufficiently to clear the side of the trigger 456 and to engage only its lower surface. This provides a cocking action in that the large pin 458 is now out of the way of the trigger 456 and said trigger is held from movement in response to air pressure at 186a only by the upper, and smaller, pin 459.

As soon as the speeds of the roller 412 and the shaft 413 become synchronized, the projection 422 on part 417 is no longer urged rightwardly. This will permit the part 417 to move leftwardly under the urging of the spring surrounding the pin 459 and thereby move the

pin 459 upwardly and release the trigger 456 to move under the urging of the fluid pressure in line 186a into its broken line position as shown in Figure 20. This will move the valve core 451 leftwardly and thereby open the valve 184a. Opening of valve 184a will effect a shifting of the main transmission in the same manner as the opening of the valve 184 effects such shifting in the form of the device shown in Figures 1 to 15.

The lengths of the respective pairs of rods 442 and 444 will vary with respect to the several gear ratios concerned so that for any given gear ratio the roller 412 will be positioned by said rods in a predetermined radial location on the disk 431 and will reach synchronism with the shaft 413 and thus react as above described only with respect to a particular, selected, speed ratio between the shafts 413 and 429.

The space between the opposed ends of the rods 442 and 444 is provided to permit slightly different ratios of speed to exist between the shafts 413 and 429 at the instant of tripping the trigger 456 according to whether an upshift or a downshift operation is being performed and thereby whether shaft 413 is going faster or slower than roller 412 prior to synchronism. In this structure, the plate 438 being urged by the roller 412 rightwardly against the rod 444 on an upshift and it being urged by said roller leftwardly against the rod 442 on a downshift. The amount by which synchronism of the roller and the shaft 413 anticipates exact synchronism of the gears being meshed is determined by the length of whichever of the rods 442 and 444 is, in a given case, controlling the position on the disk 431 of the roller 412.

Completion of the shift and deenergizing of the line 208 will result in deenergizing of the inlet 186a and will permit the spring 454 to return the toggle mechanism to the valve closing position and the pins 458 and 459 to the position shown in Figure 19 before the next shifting operation.

Figures 21 to 23

While all of the foregoing description has assumed that the detector unit 100 and the mechanism associated therewith is of a mechanical and/or hydraulic nature, even though various specific types thereof are contemplated within the scope of the invention, it should be recognized that other kinds of apparatus, such as electrical, are also possible and feasible.

For example, there is schematically illustrated in Figure 21 a type of device utilizing electrical and optoelectrical means for functioning in place of the detector unit 100 in carrying out the purposes of the invention.

In Figure 21 the engine shaft 6 is shown connected through a flywheel and clutch assembly 7 to an input shaft 2, and this shaft is connected through a series of main gear ratios to an output shaft 3 in the same manner as shown in Figures 1 to 15. Here, however, the shaft 3 drives a generator type tachometer output device 470, which device is connected through convenient means, such as an electrical conductor 471 to a speed responsive device 472 including a rotatable disk having a radial slot 473. Either the input shaft 2 or the countershaft 4 which is permanently gear connected thereto, here the countershaft 4, is electrically connected from an output unit 474, similar to the device 470, through a conductor 476 and through one of a group of gear ratio condensers 477 to a second speed responsive device 478 including a rotatable disk provided with a radial slot 479. A light source 481 is positioned to direct a beam of light through the slots 479 and 473, when same are in alignment, onto an opto-electrical device 482. The output of said last named device 482 is conducted through an amplifier 483 and provides a signal, such as by opening a solenoid controlled valve, which is comparable functionally to the opening of the valve 184 in the detector unit 100. Selection of one of the gear ratio condensers 477 by means operating simultaneously with the knob 76 (Figures 1 to 15) by which the ratio of the main transmission is se-

lected, determines the speed ratio between the countershaft 4 and the output shaft 3 at which the disks 478 and 472 will be in synchronism. When said disks are in synchronism, the light beam from the source 481 will produce a signal from the opto-electrical device 482 and signal the completion of a shift in the same general manner set forth above in connection with Figures 1 to 15.

A slightly modified system is schematically indicated in Figure 22. Here an output generator 491 is driven by the output shaft 3 and a second output generator 492 is driven by the shaft 4, the potential of each generator output being proportional to its speed. The outputs of these generators are each rectified by the rectifiers 493 and 494 and applied to the respective windings of a fall-off relay 496, with the output of the rectifier 494 being conducted through a selected one of a plurality of gear ratio resistors 497.

A spring 495 urges the contacts of the relay 496 together and the force of the spring is opposed by the windings of relay 496 proportionately to the potential applied to each of them, which windings are, however, wound oppositely with respect to each other. Thus, so long as either winding is energized with greater potential than the other, the relay is urged open, but when the potentials balance and cancel each other, the relay will respond to the spring 495 and close. This will provide a signal, which may then be utilized for opening the valve 184 and initiating the shift. It will be evident that the one of the resistors 497 chosen will preselect the speed ratios between the shafts 3 and 4 at which such signal will be given and thereby the proper point of synchronization may be predetermined.

Figure 23 shows a system generally similar to Figure 22, excepting only that here the shafts 3 and 4 drive the rotor and stator, respectively, of a generator 501. The windings of said rotor and stator are then connected to a fall-off relay, one side thereof going through gear ratio resistors, for functioning in the same general manner as above discussed in connection with Figure 22.

In view of the foregoing, it will be evident that all of the detector devices shown in Figures 17 to 23, inclusive, may readily be designed to provide a shift completing signal as far ahead of the synchronization of the shiftable elements in the main transmission as desired. Hence, the advantages of anticipating actual synchronization of the main transmission in initiating completion of any given shifting operation are fully met by these alternate detector devices.

Figures 24 and 25

Referring to Figure 24, there is shown schematically the operation of the apparatus as a fully automatic transmission, rather than a manually selectable transmission. Here, an automatic controlling device 400 of any convenient type, such as speed responsive, torque responsive or other known type, is arranged with its output mechanically connected to the control rod 75. Thus, assuming the controlling device to be torque responsive, variations in the torque load demanded of a critical part of the vehicle, such as the propeller shaft of a truck, will result in suitable manipulation of the control rod 75 and the transmission will be thereby subject to fully automatic control.

In Figure 25 there is schematically indicated means by which the operating rod 75 may be subjected to semi-automatic, or push button, control. Here the rod 75 is made of nonmagnetic material and contains a bar 506 of magnetic material near its outer end. A power source 502 is connected through a series of push buttons 503 to a suitably tapped solenoid winding 504 in such a manner that selection of one of said push buttons will determine the length of said solenoid which is energized, thereby determining the position to which the bar 506 will center itself and thus in turn determining the position of the operating rod 75.

It will be understood that neither of the modifications

indicated in Figures 24 and 25 are intended to disclose operating mechanism as such but are merely exemplary of the wide range of use, and many types of automatic or semi-automatic control, in addition to manual control, to which the mechanism of the invention is readily adapted for use.

While specific examples of apparatus have been herein used to illustrate the principles of the invention, it will be appreciated that many modifications may be made to the apparatus herein specifically shown without departing from the scope of the invention. Particularly, while a compressed air system has been utilized as illustrating a fluid pressure system for operating the respectively controlled parts and an electrical system has also been utilized for illustrating a modification, it will be understood that other types of energy transfer means may be freely used without departure from the broad principles of the invention. Accordingly, the hereinafter appended claims shall be understood to cover these and other modifications which will be apparent to those acquainted with apparatus and methods of the general type herein concerned, excepting as said claims by their own terms expressly require otherwise.

What is claimed is:

1. In a transmission, the combination comprising: a change speed gear system including shiftable, interengageable, toothed elements; means detecting the relative speeds of a given interengageable group of said toothed elements, said detecting means including means for delivering a signal at a predetermined time before said given group of toothed elements attains exact synchronization on either an upshift or a downshift; means responsive to said given signal for effecting interengagement of said group of toothed elements.

2. In a transmission, the combination comprising: a change speed gear system including pairs of shiftable, interengageable, toothed elements; detecting means for detecting, but not affecting, the relative speeds of a selectable pair of said toothed elements, said detecting means being selected simultaneously with the selection of said pair of toothed elements to be interengaged; said detecting means including means for delivering a signal at a predetermined time before said selected pair of toothed elements attains exact synchronization thereof on either an upshift or a downshift; means responsive to said signal for effecting interengagement of said selected pair of toothed elements.

3. In a transmission, the combination comprising: a change speed gear system including interengageable toothed elements and pressure fluid responsive means for shifting said elements; means for detecting the relative speeds of a selected interengageable group of said toothed elements, said detecting means including means for delivering a signal at a predetermined time before said selected group of toothed elements attains exact synchronization on either an upshift or a downshift; valve means, including a valve element shiftable in response to said signal, for controlling the supply of fluid pressure for effecting interengagement of said selected group of toothed elements.

4. In a transmission, the combination comprising: a change speed gear system including shiftable, interengageable toothed elements; means for detecting the relative speeds of a selected interengageable group of said toothed elements, said detecting means including means for delivering a signal at a predetermined time before said selected group of toothed elements attains exact synchronization on an upshift or a downshift; means for urging said selected group of toothed elements into interengagement; blocking means for preventing said selected group of toothed elements from interengaging; and means responsive to said signal for rendering said blocking means ineffective whereby said selected group of toothed elements may be interengaged.

5. A transmission according to claim 4 including a pres-

5

sure fluid actuated piston and cylinder assembly connected for urging said selected group of toothed elements into interengagement; a second pressure fluid actuated piston and cylinder assembly connected for opposing interengagement of said selected group, said second assembly being adapted to exert a greater force than does said first assembly whereby said selected group is disengaged whenever said second assembly is actuated; a valve for controlling actuation of said second assembly; and means responsive to said signal for shifting said valve whereby actuation of said second assembly is terminated and said selected group of toothed elements interengage under the urging of said first assembly.

6. In a transmission, the combination comprising: an input shaft; a countershaft rotatable by said input shaft; an output shaft; a plurality of sets of shiftable, interengageable gears on said countershaft and on said output shaft whereby said output shaft may be driven at a variety of speeds by said countershaft; brake means for decelerating said countershaft; means for detecting the relative speeds of rotation of a selected set of gears, said detecting means delivering a signal at a predetermined condition of synchronization of said selected set of gears before exact synchronization thereof; means responsive to said signal for effecting interengagement of said selected set of gears; and means also operable during an upshift of said transmission for actuating said brake means to decelerate said countershaft, said last-named means being responsive to said signal for removing said brake means from said countershaft after said signal is delivered.

7. In a transmission, the combination comprising: an input shaft; a change speed gear system including shiftable interengageable toothed elements; an engine and means including a clutch for connecting said engine to said change speed gear system; means for selecting a group of said toothed elements for interengagement; means operable in response to actuation of said selecting means for detecting the relative speeds of a selected interengageable group of said toothed elements, said detecting means delivering a signal at a predetermined condition of synchronization of said selected group of toothed elements before exact synchronization thereof; means responsive to said signal for effecting interengagement of said selected group of toothed elements; and means also responsive to operation of said selecting means for actuating said clutch to disconnect said engine from said change speed gear system.

8. In a transmission, the combination comprising: an input shaft; an engine and means including a clutch for selectively connecting said engine to said input shaft; a countershaft rotatable by said input shaft; a brake on said countershaft for decelerating same; a plurality of sets of shiftable, interengageable gears on said countershaft and on said output shaft whereby said output shaft may be driven at a variety of speeds by said countershaft; a pressure fluid actuated piston and cylinder shifting assembly for each of said sets and adapted to cause interengagement of the gears thereof; a pressure fluid actuated piston and cylinder neutralizing assembly connected for opposing interengagement of the gears of said sets, said neutralizing assembly being adapted to exert a greater force than does each of said shifting assemblies, whereby the sets of gears are disengaged wherever said neutralizing assembly is actuated; means for selecting a set of said gears for interengagement, said selecting means connecting the shifting assembly of the selected set for supplying fluid pressure thereto to urge said shifting assembly to move the gears in said selected set into interengagement; a valve for controlling actuation of said neutralizing assembly; means operable in response to actuation of said selecting means for detecting the relative speeds of a selected set of gears, said means delivering a signal at a predetermined condition of synchronization of said selected set of gears; means responsive to said signal for shifting said valve whereby actuation of said neutralizing

assembly is terminated so that said selected set of gears may interengage under the urging of the shifting assembly for the selected set; fluid operated means for actuating said clutch and means for supplying pressure fluid to said clutch actuating means in response to operation of said selecting means for actuating said clutch to disconnect said engine from said input shaft; fluid operated means for actuating said brake and means responsive to said selecting means during an upshift of said transmission for supplying fluid for actuating said brake means to decelerate said countershaft.

9. In a transmission shifting apparatus, the combination comprising: a set of change speed gearing including a plurality of shiftable, interengageable, toothed elements; power operated means for effecting shifting of an interengageable pair of said shiftable toothed elements; a detecting unit connected to the input and output, respectively, of said change speed gear set for responding to, but not changing, the relative speeds of said pair of toothed elements, said detecting unit including means arranged for indicating a condition of synchronization of the relative speeds of said pair of toothed elements at a point a preselected amount ahead of exact synchronization of said pair of elements; means responsive to said indicating by said detecting unit for controlling operation of said power operated means and thereby effecting shifting of said pair of toothed elements of said change speed gear unit.

10. In a transmission shifting apparatus, the combination comprising: a change speed transmission having an input shaft and an output shaft and having a plurality of sets of shiftable, interengageable gears whereby said output shaft may be driven at a variety of speeds with respect to the input shaft; a detecting unit including devices responsive to the speed ratio between the speeds of rotation of said input and output shafts, respectively, said devices being so connected that they do not materially affect the speed of rotation of said input and output shafts; signalling means responsive to a predetermined condition of synchronization of said devices; means responsive to a signal from said signalling means for effecting a shift of a selected set of gears in said change speed transmission; ratio changing means in said detecting unit for changing the effect on said signalling means of said speed ratio, said ratio changing means having at least two selectable values so that said devices will attain a predetermined condition of synchronization ahead of a corresponding predetermined condition of synchronization of the gears in said selected set on either an upshift or downshift of said transmission.

11. In a transmission shifting apparatus, the combination comprising: a change speed transmission having an input shaft and an output shaft and having a plurality of sets of shiftable, interengageable toothed elements whereby said output shaft may be driven at a variety of speed ratios with respect to said input shaft; a detecting unit having a main shaft and a countershaft and a plurality of sets of shiftable, interengageable toothed elements corresponding to the sets in said transmission; means connecting the main shaft and countershaft of said detecting unit for being driven by the input and output shafts of said change speed transmission, said connecting means including ratio change gear means for driving the main and countershafts thereof at a plurality of selectable speed ratios with respect to the input and output shafts of the change speed transmission so that the toothed elements in a selected set in said detecting unit may attain synchronization before the toothed elements in the corresponding selected set in the change speed transmission, regardless of whether the change speed transmission is being upshifted or downshifted, by selection of an appropriate ratio in said ratio change gear means.

12. In a transmission shifting apparatus, the combination comprising: a change speed transmission having an input shaft and an output shaft and having a plurality of

sets of shiftable, interengageable toothed elements whereby said output shaft may be driven at a variety of speed ratios with respect to said input shaft; a detecting unit having a main shaft and a countershaft and a plurality of sets of shiftable, interengageable toothed elements corresponding to the sets in said transmission whereby said main shaft and said countershaft may be driven at a selected speed ratio with respect to each other corresponding to a first speed ratio in said change speed transmission by selection and interengagement of a selected set of said elements; means connecting the main shaft and countershaft for being driven by said input and output shafts, said connecting means including a first device for causing said main shaft and said countershaft to rotate at a second speed ratio which is slightly greater than said selected speed ratio and also including a second device for causing said main shaft and countershaft to rotate at a third speed ratio which is slightly less than said selected speed ratio, said first and second devices alternatively operable so that the toothed elements in a selected set in said detecting unit may attain synchronization before the toothed elements in the corresponding selected set on the change speed transmission, regardless of whether the change speed transmission is being upshifted or downshifted, by operation of the appropriate one of either said first or said second device.

13. A transmission shifting apparatus according to claim 12 including a signalling member shiftable when the toothed elements in a selected set in said detecting unit attain synchronization; blocking means preventing shifting of said signalling member until said synchronization is attained; and means responsive to shifting of said signalling member for interengaging the toothed elements in the corresponding set in the change speed transmission.

14. A detecting unit for use with a change speed transmission having input and output elements; a pair of rotatable reference elements within said detecting unit and means providing a signal upon attainment of substantially exact synchronization of rotative speeds by said reference elements; means driving one of said reference elements from the input of said transmission and at a predetermined speed ratio with respect thereto; means driving the other reference element from the output of said transmission and at a predetermined speed ratio with respect thereto; a ratio changing device connected to one of said two last named means for changing the speed ratio by which one of said reference elements is driven on both the upshift and the downshift of said transmission in such a manner that said reference elements will attain substantially exact synchronization a predetermined amount of time ahead of the exact synchronization of the change speed transmission.

15. The apparatus defined in claim 14 wherein the detecting unit comprises: a main shaft and a countershaft; pairs of gears interengaging each other on said shafts, of ratios equal to corresponding gear ratios in said transmission but reversed with respect thereto; means driving the countershaft of said detecting unit at a constant ratio with respect to the speed of the output of said transmission; a ratio change gear set on the main shaft of said detecting unit and means driving said main shaft from the input element of said transmission through said ratio change gear set, said ratio change gear set being shiftable to drive said main shaft of the detecting unit at a speed higher than that of the input element of said transmission on a downshift and at a lower speed on an upshift, and said signal being given upon synchronization of the gears in said detector unit corresponding to the next intended shift ratio of said transmission.

16. The apparatus defined in claim 14 wherein the detecting unit comprises: a main shaft and a countershaft; pairs of gears interengaging each other on said shafts and being of ratios equal to corresponding gear ratios on said transmission but reversed with respect thereto;

means driving one of said shafts of said detecting unit at a constant ratio with respect to the speed of one of the input or the output elements of said transmission; a ratio change gear set, and means driving the other shaft of said detecting unit from the other of the input and output elements of said transmission through said ratio change gear set, said ratio change gear set being so shiftable that said other shaft of the detecting unit will be driven at a speed higher than that of the input element of said transmission on a downshift and at a lower speed on an upshift, and said signal being given upon synchronization of the gears in the detector unit corresponding to the next intended shift ratio of said transmission.

17. In a device for power shifting a set of change speed gears, the combination comprising: a plurality of shift rods, each having means for engaging the shiftable elements of said change speed gear set; pressure fluid means arranged for moving said rods selectively in an axial direction; a stop on each of said rods; a first return means slidably arranged over each of said rods and adapted for engaging one side of said stops and a second return means slidably arranged over each of said rods and adapted for engaging the other side of said stops; a cylinder; a piston slidable within said cylinder; means connecting said first return means to said piston and means connecting said second return means to said cylinder, said cylinder being supported on and by said second return means; whereby pressure supplied within said cylinder to said piston will urge movement of said return means toward each other and will cause same to engage said stops and thereby return to a predetermined center position any of said rods which are moved away therefrom and will hold said rods in said center position; pressure release means removing pressure from said cylinder and means for applying pressure to one of said rod moving means for effecting a shift.

18. The device defined in claim 17 wherein said change speed gears are driven by an engine and a clutch selectively connects and disconnects said engine and said change speed gears; including pressure responsive means actuated simultaneously with the imposition of pressure on said cylinder for releasing said clutch and further pressure release means comprising a valve having a housing element and a slider element, one of said elements being connected to said cylinder and the other of said elements being connected to said piston; said means connecting the cylinder with said valve being so arranged that a predetermined relative movement of said piston and said cylinder will move said valve to an exhaust position and thereby relieve pressure from said pressure responsive means.

19. A shifting system for shifting a set of change speed toothed elements, comprising in combination: a set of shiftable change speed gears and shift actuating means adapted for selective movement to effect a selected shifting operation; a source of energy; neutral energizing means adapted when energized to urge said shift actuating means toward neutral position; shift energizing means adapted when energized to urge a selected one of said shift actuating means toward a shifted position, the force applied by said shift energizing means to a given shift actuating means in a shifting direction being less than the force applied to said shift actuating means by said neutral energizing means for urging said shift actuating means toward its neutral position; a selector having a set of positions, means responsive to positioning of said selector in one of its positions for energizing one of said shift energizing means and holding same energized; means for initiating energization of said neutral energizing means and for holding same energized, said initiating means being operable prior to movement of said selector into its next position; a detector unit having at least two parts, each part being responsive to the speed of one of the toothed elements about to be shifted and arranged for indicating a predetermined condition of synchronization

of the relative speeds of said toothed elements, said condition bearing a predetermined relationship to the point of exact synchronization of said toothed elements; trigger means actuated by said detector unit upon its reaching said condition and means responsive to actuation of said trigger means for deenergizing said neutral energizing means whereby the urging of said shift actuating mechanism into its neutral position is terminated and the force urging said shift actuating mechanism into a shifted position is permitted to effect immediate movement of said shift actuating mechanism into a shifted position.

20. A shifting system for shifting a set of change speed toothed elements, comprising in combination: a set of shiftable change speed toothed elements and shift actuating means adapted for selective movement to effect a selected shifting operation; a selector having a set of primary positions and a set of secondary positions; a source of energy; neutral energizing means adapted when energized to urge said shift actuating means toward neutral position; shift energizing means adapted when energized to urge a selected one of said shift actuating means toward a shifted position, the force applied by said shift energizing means to a given shift actuating means in a shifting direction being less than the force applied to said shift actuating means by said neutral energizing means for urging said shift actuating means toward its neutral position; means energized by the positioning of said selector in one of its secondary positions for initiating energization of said neutral energizing means and other means holding same energized following said initiation; other means responsive to positioning of said selector in one of its primary positions for energizing one of said shift energizing means and holding same energized; a detector unit having at least two parts, each responsive to the speed of the toothed elements about to be shifted and arranged for indicating a predetermined condition of synchronization of the relative speeds of said toothed elements, said condition bearing a predetermined relationship to the point of exact synchronization of said toothed elements; trigger means actuated by said detector unit upon its reaching said condition and means responsive to actuation of said trigger means for deenergizing said neutral energizing means; whereby the urging of said shift actuating mechanism into its neutral position is terminated and the force urging said shift actuating mechanism into a shifted position is permitted to effect movement of said shift actuating mechanism into a shifted position.

21. The device defined in claim 20 wherein said secondary positions are located intermediate said primary positions.

22. The device defined in claim 20 wherein the predetermined condition of said detector means is a point ahead of exact synchronization of said toothed elements in either an upshift or a downshift direction.

23. The device defined in claim 20 including speed change means between said detector unit and said set of change speed toothed elements for causing said detector unit to indicate synchronization prior to exact synchronization of the toothed elements about to be shifted, said speed change means being shiftable for so anticipating said exact synchronization in connection with either an upshift or a downshift of said set of change speed toothed elements; and means associated with said selector and responsive to a change in direction of movement of said selector for effecting a shifting of said speed change means.

24. A shifting system for shifting a set of change speed toothed elements, shiftable between a neutral position and shifted positions, comprising in combination: shift effecting means which, when actuated, moves a selected portion of said shiftable toothed elements into a desired shifted position and which, when all of said means are centered, moves said toothed elements into said neutral position; shift energizing means arranged with respect to

each of said shift effecting means for effecting movement thereof in a shifting direction; neutral energizing means arranged with respect to said shift actuating means for returning and holding said toothed elements in a neutral position; a shift selector having energizing positions and a source of energy, said energizing positions each directing said energy from said source to one of said shift energizing means; means for conducting energy to said neutral energizing means for returning said shift actuating means to neutral position and holding same in neutral position, said neutral energizing means exerting a greater force on said shift actuating means than is exerted by said shift energizing means; a detecting unit responsive to the relative speeds of that portion of said shiftable toothed elements which it is next desired to shift and capable of providing a signal when said relative speeds have reached a predetermined relationship with each other; means responsive to said signal for deenergizing said neutral energizing means whereby the shift energizing means is enabled to function and effect a shift.

25. A system according to claim 24 wherein said detecting unit includes a set of shiftable toothed elements corresponding to said set of change speed toothed elements; means for driving the toothed elements in said detecting unit at a speed ratio bearing a predetermined relationship to the speed ratio of the change speed toothed elements, said driving means including a first device for driving the detecting unit toothed elements at a speed ratio which is slightly greater than said speed ratio of said change speed toothed elements, said driving means also including a second device for driving the detecting unit toothed elements at a speed ratio which is slightly less than said speed ratio of said change speed toothed elements so that the toothed elements in said detecting unit corresponding to the said selected portion of change speed toothed elements may attain synchronization before the selected portion of the change speed toothed elements, regardless of whether the change speed transmission is being upshifted or downshifted, by operation of the appropriate one of either said first or said second device.

26. A system for shifting a set of change speed toothed elements, shiftable between a neutral position and shifted positions comprising in combination: shift effecting means which when actuated move a selected portion of said shiftable toothed elements into a desired shifted position and which, when all of said means are centered, moves said toothed elements into said neutral position; shift energizing means arranged with respect to each of said shift effecting means for effecting movement thereof in a shifting direction; neutral energizing means arranged with respect to said shift effecting means for returning and holding said toothed elements in a neutral position; a shift selector having energizing positions and a source of energy, said energizing positions each directing said energy from said source to one of said shift energizing means; said shift selector also having intermediate positions and other means cooperating therewith so that when said selector is in an intermediate position energy is conducted to said neutral energizing means for returning said shift effecting means to neutral position and holding same in neutral position, said neutral energizing means exerting a greater force on said shift effecting means than is exerted by said shift energizing means; a detecting unit responsive to the relative speeds of that portion of said shiftable toothed elements which it is next desired to shift and capable of providing a signal when said relative speeds have reached a predetermined relationship with each other; means responsive to said signal for deenergizing said neutral energizing means; whereby the shift energizing means is enabled to function and effect a shift.

27. The device defined in claim 26 wherein said inter-

mediate position of the shift selector is linearly between two energizing positions.

28. The device defined in claim 26 wherein said intermediate position of said shift selector is laterally off-set from a line connecting two energizing positions and means are provided causing said shift selector to travel through an intermediate position in its path of travel from one energizing position to another energizing position.

10 29. The device defined in claim 26 wherein said detecting unit includes a plurality of speed indicating parts, each corresponding to a pair of said toothed elements and the energy applied to a selected one of said shift energizing means is also utilized for selecting the portion of said detecting unit corresponding to the next shift to be made in said change speed toothed elements.

20 30. The device defined in claim 29 wherein said detecting unit comprises a pair of shafts and pairs of shiftable toothed elements arranged between said shafts in ratios corresponding to the ratios of said change speed toothed elements; shifting means responsive to said selector for urging shifting of one of said last-mentioned pairs of toothed elements and a blocker to prevent such shifting prior to substantial synchronization of said one of said last-mentioned pairs of toothed elements; means responsive to movement of said shifting means upon the completion of a shift in said detecting unit for providing said signal.

30 31. The device defined in claim 30 wherein the energy applied to one of said shift energizing means is also applied to the corresponding one of the shifting means in said detecting unit whereby shifting of said detecting unit is urged immediately upon energizing of said shift energizing means and is completed as soon as the blockers therein permit same to be completed; and wherein completion of movement of the shifting means of said detecting unit operates to discharge the energy from said neutral holding means.

40 32. The device defined in claim 26 wherein said detecting unit is arranged to complete its own shifting and thereby provide said signal at a point in time slightly ahead of the exact synchronization of the corresponding shiftable toothed elements in the main gear set; shiftable means within said detecting unit for changing said point to correspond to one of an upshift or a downshift in said change speed toothed element set and means on said selector reacting to a change in the direction of movement of the manually operated portion thereof for actuating said last named shiftable means.

45 33. The apparatus defined in claim 26, including a clutch located between said change speed toothed element set and a source of motive power therefor; means actuated simultaneously with the introduction of energy into said neutral energizing means for disconnecting said clutch.

50 34. The apparatus defined in claim 33, including other means acting immediately following commencement of a shifting movement out of neutral position for engaging said clutch.

55 35. The apparatus defined in claim 26 including a brake on the countershaft of said shiftable change speed toothed element set and means associated with said shift selector to energize same simultaneously with the energization of said neutral energizing means but only between shifts in an upshift direction.

60 36. The apparatus defined in claim 26 including means effecting manual release of the energy within the neutral energizing means.

65 37. The device defined in claim 26 including a relay in one position conducting energy from said source to said neutral energizing means and in a second position blocking energy from said source from said neutral energizing means, said second position also releasing energy previously applied to said neutral energizing means; means

70 75

including a manually actuated device for causing said relay to be shifted from said energy conducting to said energy blocking position.

38. A detecting unit for use with a transmission including: a plurality of pairs of shiftable elements arranged for selectively effecting a plurality of driving ratios between an input and an output shaft associated therewith, the combination comprising: a pair of electrical generation means operatively associated respectively with said input and output shafts and providing output signals of character varying proportionately to the speed of operation of said input and output shafts; a sensing means effecting a comparison between said output signals and utilizing same for determining and signalling the condition of synchronism in the speed of rotation of said generation device; manually operable means for controlling the relationship between said output signals and said sensing means for effecting said signalling at a predetermined rate of relative motion between said input shaft and said output shaft.

39. A detecting unit for use with a transmission including an input and an output shaft and having a plurality of pairs of shiftable elements arranged for selectively effecting a plurality of driving ratios between said input and output shafts, the combination comprising: a pair of electrical devices associated with said input and output shafts, respectively, and adapted for providing an electrical output of character varying in proportion to the speed of said input and output shafts; sensing means responsive to the character of said electrical output for providing a signal at a predetermined comparative condition of said respective electrical outputs; manually operable means interposed between one of said speed responsive means and one side of said sensing means for varying the relationship between the character of electrical output produced by said speed responsive means and that applied to said one side of said sensing means; and means responsive to said signal for effecting a shift of said transmission.

40. A detector unit according to claim 39 wherein said sensing means includes means for giving a signal at a moment when said electrical outputs are in a comparative condition corresponding to a nonsynchronous relationship between the next pair of shiftable elements to be shifted but at which moment said next pair are approaching exact synchronization so that by the time said next pair of shiftable elements are approaching engagement, they will be rotating substantially at exact synchronization.

41. A detector unit for use with a transmission including an input and an output shaft and having a plurality of pairs of shiftable elements arranged for selectively effecting a plurality of driving ratios between said input and output shafts, the combination comprising: a pair of electrical potential producing devices associated with said input and output shafts and adapted for providing an electrical signal of magnitude varying in proportion to the speed of said input and output shafts; sensing means responsive to the occurrence of a predetermined ratio between the magnitudes of said signals produced by both of said devices for providing a shift initiating signal; manually operable means interposed between one of said speed responsive means and one side of said sensing means for varying the ratio between the magnitude of signal produced by said one speed responsive means and that applied to said one side of said sensing means; and means responsive to said shift initiating signal for effecting a shift of said transmission.

42. A detector unit according to claim 41 wherein said sensing means includes means for giving a signal when the magnitude of said electrical signals are of a ratio corresponding to a nonsynchronous, but approaching exact synchronization, condition of the next pair of elements to be shifted so that when the shifting movement of said next pair has progressed so that said next pair are ap-

proaching interengagement they will be rotating substantially at exact synchronization.

43. A detector unit for use with a transmission including an input and an output shaft and having a plurality of pairs of shiftable elements arranged for selectively effecting a plurality of driving ratios between said input and output shafts, the combination comprising: a pair of electrical potential producing devices associated with said input and output shafts and adapted for providing a series of electrical signals of frequency varying in proportion to the speed of said input and output shafts; sensing means responsive to the occurrence of a predetermined ratio between the frequency of said signals produced by both of said devices for providing a shift initiating signal; manually operable means interposed between one of said speed responsive means and one side of said sensing means for varying the ratio between the frequency of signals produced by said one speed responsive means and that applied to said one side of said sensing means; and means responsive to said shift initiating signal for effecting a shift of said transmission.

44. A detecting unit for use with a change speed transmission having input and output elements, the combination comprising: a first rotatable shaft drivingly connected to one of said elements, a second rotatable shaft drivingly connected to the other of said elements, said first and second shafts being supported co-axially and for limited longitudinal movement with respect to each other, means responsive to longitudinal movement of said shafts with respect to each other for providing a signal; means supporting said first and second shafts for moving same longitudinally of each other in response to attainment of a predetermined condition of synchronization of said input and output elements.

45. A detecting unit for use with a change speed transmission having input and output elements, and a series of sets of rotatable toothed elements, interengagement of the toothed elements in one set causing a predetermined speed ratio to be obtained between said input and output elements, the combination comprising: a first rotatable shaft drivingly connected to one of said elements, a second rotatable shaft supported co-axially with and for longitudinal movement with respect to said first shaft, slider means mounted about said second shaft for rotation about the axis of said shaft and for movement longitudinally of said shaft; individually actuatable and controllable stop means associated with each of said sets of toothed elements, one of said stop means being adapted for contacting said slider means and limiting longitudinal movement thereof along said second shaft in conjunction with interengagement of the set of toothed elements associated with said one stop means; means drivingly connected to the other of said elements for rotating said slider about said second shaft, said rotation of said slider causing longitudinal movement thereof when said second shaft is rotating at a different speed from said slider, contact between stop means and said slider effecting a driving connection between said second shaft and said means for rotating said slider; interengaging means on said first and said second shafts permitting relative longitudinal movement thereof in response to attainment of a predetermined condition of synchronization of said input and output elements, and signal means responsive to relative longitudinal movement of said shafts.

46. The combination of claim 45 wherein said means for rotating said slider includes a rotatable disk contacting said slider, said slider being internally threaded and engaging external threads on said second shaft.

47. The combination of claim 45 wherein said interengaging means on said first and second shafts includes a longitudinally notched collar on one of said shafts and a member on the other of said shafts loosely fitting within said notch, said notch and said member having cooperating wedge surfaces whereby said member may move rela-

tive to such notch, such relative movement effecting relative longitudinal movement of said shafts.

48. A change speed transmission, including in combination: an input shaft; a countershaft rotatable by said input shaft; an output shaft; a plurality of sets of shiftable interengageable change speed gears on said countershaft and on said output shaft whereby said output shaft may be driven at a variety of selectable speeds with respect to said input shaft; pressure fluid movable shift rods connected for selectively interengaging the gears in one of said sets at a time; a neutralizing assembly including a cylinder and piston and means connecting said assembly whereby said shift rods are placed in neutral position upon energization of said neutralizing assembly, said neutralizing assembly being capable of exerting greater force than is exerted on said shift rods to shift same whereby said shift rods are in neutral whenever said neutralizing assembly is energized; a detector unit including a main shaft, a countershaft and a plurality of sets of shiftable interengageable gears corresponding to the sets of change speed gears; pressure fluid actuated shift rods for shifting said detector unit gear sets; means connecting the main and countershafts of said detector unit for being driven by said input and output shafts, said connecting means including selectable ratio change gear means for driving the main and countershafts thereof at a plurality of selectable speed ratios with respect to the input and output shafts of the change speed transmission so that a selected set of detector unit gears may achieve synchronization before the corresponding set of change speed gears regardless of whether the change speed gears are being upshifted or downshifted; shiftable means responsive to synchronization of a selected set of detector unit gears for signalling such synchronization; a selector member having a set of positions, said selector member providing for pressure fluid energization of shift rods for corresponding sets of said change speed gears and said detector unit gears in each of its positions; means for energizing said neutralizing assembly; and means responsive to said signal for deenergizing said neutralizing assembly whereby a selected set of change speed gears may be interengaged substantially at synchronization.

49. A transmission according to claim 48 including a clutch connecting the input shaft to the engine and pressure fluid operated actuation means therefor; a brake on said countershaft and pressure fluid operated actuation means therefor; means for energizing said clutch actuation means and disengaging said clutch when said neutralizing assembly is energized; and means for energizing said brake actuation means to apply said brake on said countershaft when said shift rods for said change speed gears are in neutral during an upshift.

50. A transmission according to claim 49 including a first valve connected to said neutralizing assembly for controlling energization thereof; a second valve connected to said neutralizing assembly and operable in response to the position thereof; third valve means which includes said shiftable means whereby said third valve means is operable in response to synchronization of a selected gear set in said detector unit; means connecting said clutch actuation means to said first valve whereby said clutch is disengaged by pressure fluid when said neutralizing assembly is energized; conduit means connecting said third valve means to said first valve so that said first valve is shifted and said neutralizing assembly deenergized upon movement of said shiftable means in response to synchronization of a selected gear set in said detector unit; means connecting said brake actuation means to said second valve for pressure fluid actuation thereof during an upshift when said neutralizing assembly is in neutral position; and means for permitting said clutch to reengage when said neutralizing assembly reaches neutral position during a downshift.

51. A detecting unit for use with a change speed trans-

mission having input and output elements and having selectively interengageable toothed elements for providing selectable speed ratios between said input and output elements; a pair of rotatable reference means within said detecting unit and means providing a signal upon attainment of substantially exact synchronization of the relative speeds of said reference means; means driving one of the reference means from the input element of said transmission and at a predetermined speed ratio with respect thereto; means driving the other reference means from the output element of said transmission and at a predetermined speed ratio with respect thereto; ratio drive means connected to one of said two last-named means for driving one of said reference means in such a manner that the said last-named reference means will attain substantially exact synchronization with the other reference means a predetermined amount of time ahead of exact synchronization of the toothed elements next to be engaged of the change speed transmission on either an upshift or a downshift thereof.

52. A detecting unit according to claim 51 wherein said detecting unit is a miniature transmission having a main shaft, a countershaft and pairs of interengaging gears on said shafts to provide speed ratios corresponding to the speed ratios in the change speed transmission, the gears of one of said shafts being normally rotatable with respect thereto; and clutch means on said one shaft for clutching the gears on said one shaft thereto.

53. A shifting system for shifting a set of change speed toothed elements, comprising in combination: a set of shiftable change speed toothed elements and shift rods adapted for selective movement to effect a selected shifting operation; a source of energy; neutral energizing means adapted when energized to urge said shift rods toward neutral position; shift energizing means adapted when energized to urge a selected one of said shift rods toward a shifted position; a selector movable through a set of positions, said selector when in its respective positions permitting the supply of energy to the respective shift energizing means; means operable before said selector moves from one position thereof to another for energizing said neutral energizing means; a detector unit having at least two parts, each being responsive to the speeds of the toothed elements about to be shifted and arranged for indicating a predetermined condition of synchronization of the relative speeds of said toothed elements prior to exact synchronization thereof; trigger means actuated by said detector unit for de-energizing said neutral energizing means whereby the urging of said shift rods into neutral is terminated and force is applied through said selector to urge a selected shift rod into shifted position.

54. In a transmission, the combination comprising: a change speed gear set including shiftable, interengageable, toothed elements; power operated means for shifting a given group of interengageable, toothed elements; a detecting unit connected to said change speed gear set for responding to, but not changing, the relative speeds of said given group of toothed elements, said detecting unit including means for giving a signal indicating a condition of synchronization of the relative speeds of said given group of toothed elements at a time ahead of exact synchronization of said given group of toothed elements on either an upshift or a downshift; means responsive to said signal by said detecting unit and connected to said power operated means for causing said power operated means to effect shifting of said given group of toothed elements into interengagement so that said given group of toothed elements interengage substantially at the time they are substantially in exact synchronization.

55. A transmission according to claim 54 wherein said means for giving a signal is arranged so that the signal is given at a time when said given group of toothed elements are in a nonsynchronous relationship but are approaching exact synchronization.

56. A transmission according to claim 55 wherein said transmission has an input shaft and an output shaft and a plurality of groups of selectively interengageable toothed elements for providing selectable speed ratios between said input and output shafts; said detecting unit including a pair of rotatable reference means, means for driving one of said reference means from said input shaft and means for driving the other reference means from said output shaft; modifying means including selectable means for modifying the output of at least one of said reference means so that the outputs of said reference means selectively represent, but at least one thereof is advanced with respect to the speeds of the group of toothed elements about to be interengaged on either an upshift or a downshift of the transmission, said means for giving a signal being responsive to the outputs of said reference means as modified by said modifying means so that a signal is given when said outputs are of a ratio indicating that the group of toothed elements next to be engaged are in said nonsynchronous relationship but are approaching exact synchronization.

57. A transmission according to claim 56 including an engine; a clutch for connecting said engine to said input shaft; a brake for retarding rotation of said input shaft; a fluid pressure operated piston and cylinder shifting assembly for each of said groups of toothed elements;

manually operable selecting means movable through a series of positions for selecting the group next to be engaged; means operable in response to movement of said selecting means from one position to another for placing the transmission in neutral; means operable in response to movement of said selecting means from one position to another during an upshift of the transmission for operating said clutch to disconnect the engine from said input shaft and for applying said brake to retard rotation of said input shaft; valve means operable in response to a signal by said detecting unit for supplying fluid pressure to the piston and cylinder shifting assembly for the next set of toothed elements to be engaged whereby same may be moved into interengagement substantially at the time they are in exact synchronization; and means responsive to the signal for removing said brake and permitting said clutch to re-engage.
